UNITED STATES PATENT OFFICE.

EDWARD E. CLEMENT, OF WASHINGTON, DISTRICT OF COLUMBIA, ASSIGNOR, BY
MESNE ASSIGNMENTS, TO JAMES R. GARFIELD, TRUSTEE, OF CLEVELAND, OHIO.

TELEPHONE SYSTEM.

1,230,996.

Specification of Letters Patent. Patented June 26, 1917.

Application filed March 2, 1911. Serial No. 611,923.

To all whom it may concern:

Be it known that I, EDWARD E. CLEMENT, a citizen of the United States, residing at Washington, in the District of Columbia, have invented certain new and useful Improvements in Telephone Systems, of which the following is a specification, reference being had therein to the accompanying drawing.

10 My invention relates to telephone exchange systems, and particularly to semi-automatic systems. Its general object is the improvement of such systems in divers particulars as will hereinafter appear. Among 15 particular objects may be specified the following:

To carry out a system of aggregation of units both in apparatus and circuits, from the smallest part to a complete system, so 20 that all corresponding parts are interchangeable; to use a standard two-motion selector switch for testing selection, whereby a large number of circuits may be tested in a relatively small number of motions; to provide 25 for simultaneous testing travel of primary and secondary selector switches, whereby the operator's answering time is reduced; to provide a simple and efficient test circuit for selector switches, together with ancillary 30 control of actuating and release magnets as the links are built up; to provide for a forward release impulse controlled by the calling subscriber until the called subscriber answers; to lock the calling subscriber 35 against release until after the operator answers; to provide for "killing" operators' positions automatically when vacated, and the rotation of calls among the remaining active positions; to signal the operator during 40 transmission of switch controlling impulses; to improve primary and secondary distribution of calls; to simplify the connector circuit by using the ringing selector as a side switch; to improve the release and 45 other features of the selector and connector circuits and generally simplify the same.

The invention is illustrated in the accompanying drawings in which:

Figure 1 is a skeleton diagram of the complete system and Figs. 2 to 7 are detailed diagrams as follows:

- Fig. 2 shows a subscribers' line and the primary control circuits.

Figs. 2^a and 2^b show modifications thereof.

Fig. 3 shows primary and first selector 55 switch circuits.

Fig. 3^a shows a second selector switch circuit.

Fig. 3^b is a detail of the release circuit.

Fig. 4 shows a connector switch circuit. 60

Fig. 5 shows the operator's trunk with key-set control.

Fig. 6 shows the operator's key-set and sending machine circuit.

Fig. 7 shows a subscriber's party-line. 65

Fig. 8 is a detail of primary and secondary control.

Fig. 9 is a side view of the type of switch used for selectors and connectors in this system. 70

Fig. 10 is a plan view thereof.

Fig. 11 is a detailed view of the latch for the release mechanism.

Figs. 12 and 13 are detailed views taken at right angles to each other of the spindle 75 and wipers removed from the switch frame.

In this description I will first outline the system as shown in Fig. 1, then briefly describe the various pieces of apparatus shown in Figs. 9 to 13 inclusive, and finally take 80 up the circuits in Figs. 2 to 8 inclusive, and explain their operation in detail.

In Fig. 1, each element is marked with the title by which in general it will be designated throughout the case, and enough of 85 the reference letters and numerals are shown for purposes of comparison and to gain a general understanding of the relation of the various parts of the circuits shown in the other diagrams. It may be here stated that 90 for convenience all calls will be assumed to originate at the left hand end or station, and all connections to progress toward the right, the wanted or called subscriber being assumed as the right hand subscriber in 95 every case. Of course, it will be understood that there is no such limitation in practice, but this assumption simplifies description and illustration. In this figure therefore three subscribers are shown at the left hand 100 end of the sheet whose lines terminate on multiple contacts of three primary selector switches, each of which has a pivoted wiper or contact which can be swept over the line contacts to connect with any one of them. 105 Each of these wipers forms one terminal of a first selector trunk, the other terminal of which is a similar wiper in the first selector

switch. The fixed contacts over which these wipers sweep in all the switches are usually referred to as bank contacts, and in mass as "contact banks."

5 The bank contacts of the first selector switches form the terminals of second selector trunks, each of which is connected to corresponding contacts, that is to say "multiplied," in all the first selectors. At the 10 right hand ends the second selector trunks terminate at wipers of second selector switches, and from the bank contacts of these switches the connector trunks are taken, in multiple as before, to the wipers 15 of connector switches. The banks of these connector switches contain only line terminals, just the same as the primary selectors. At the right hand end of Fig. 1 three subscribers' lines are shown, each with four 20 subscribers' stations connected to it in parallel. These are party lines, so shown for the purpose of illustrating the principle of selective ringing, which forms a part of the 25 system. They need not all be party lines however, nor is it necessary that the subscribers shown on the right of Fig. 1 should be different from those shown at the left. On the contrary, every subscriber's line, in 30 order to have complete service, must be connected to terminals in both the primary selector switches and the connector switches, since it is through the former that the subscriber when calling reaches the central office, and it is through the connector 35 switches that the central office when calling reaches the subscriber. The connections of a line to primary and connector switches are made in parallel, just as are those of each line to the several switches of either class.

40 Associated with each connector switch is an auxiliary or ringing selector switch. The wiper of this switch sweeps over contacts connected to several ringing generators, each of which generates a particular distinctive 45 character of current. At the several stations on a party line the bells are designed and adjusted so as to respond selectively and exclusively, each to its own particular kind of current only. At the last stage in 50 a connection, when the wanted subscriber's line has been picked out by the connector switch, and the ringing selector has been set so as to bring into service the proper generator, the wiper of that switch is then automatically connected through the connector 55 to the subscriber's line to ring his bell. At all other times the ringing selector remains disconnected.

The primary selector switches are controlled by the subscribers in calling, through the medium of line relays at the central office which respond to the flow of current in the subscribers' lines, and which when so energized guide and direct the primary 65 switch wipers to their respective line con-

tacts. A calling subscriber therefore gains access to the first selector trunks in the central office by his own act alone. In order to continue the connection however, from the first selector trunk to the wanted subscriber, 70 it is necessary to actuate a first selector switch, a second selector switch and a connector switch. The type of switch employed in this system is electromagnetically driven by means of current impulses of predetermined number sent in predetermined groups, 75 which move the switch wipers step by step over the bank contacts. These impulses are supplied, and the switches are controlled, by operators at the central office, who for that purpose are given access through secondary selector switches to the first selector trunks, whereby they are enabled both to receive 80 their orders from the calling subscribers, by way of the primary selectors, and to send impulses to the first selector and succeeding switches, for the purpose of making the desired connection. The secondary selector switches as will presently be seen, are initially responsive to the subscribers' acts in 85 calling. In fact, broadly speaking, their operation is the same as that of the primary selector, the flow of current in a calling subscriber's line and in the first selector trunk connected thereto causing a secondary selector switch wiper to be guided and directed automatically to a contact in its bank 90 which is connected to the first selector trunk in question.

In order to select and transmit the proper 100 impulses for line selection I provide each operator with a key-set mounted on a suitable desk, and having associated with it certain signals which guide the operator in the performance of her duties. The key-set in 105 general appearance and arrangement is quite similar to the key board of an adding machine or typewriter, consisting of a number of strips of ten keys each, numbered from one to naught in each vertical row. One of 110 the signals associated with these keys is a calling lamp, which is lighted automatically when the key set becomes connected through the secondary switch to a first selector trunk already connected to a subscriber's line 115 through a primary selector switch. Observing the signal, the operator asks the subscriber for the number wanted, and proceeds to depress the corresponding keys or buttons. She then presses a separate starting 120 key, and groups of impulses, corresponding to the buttons depressed, will thereupon be transmitted through the key-set, through the secondary selector switch and through the first selector trunk to the first selector 125 switch, causing the following operations: (1) The first selector switch is stepped around to the contact of a second selector trunk leading to a second selector switch in the thousands group corresponding to the 130

first digit set up; (2) the second selector switch is stepped around to select a connector trunk leading to a connector switch of the hundreds group corresponding to the second 5 digit set up, (this particular connector containing terminals of the line wanted); (3 and 4) the connector switch is then stepped around in response to the third and fourth groups of impulses to pick out the terminals 10 of the line wanted; and (5) the associated ringing selector having been set in response to the operation of the impulses, the wanted subscriber's bell is automatically rung.

15 Reference has been made above to "thousands groups" and "hundreds groups" of circuits. This particular switching system is known as a percentage trunking system. That is to say, the connection between any 20 two lines is effected by successive steps or successive acts of subdivision. For example, in an exchange serving ten thousand subscribers, the second selector switches would be divided into ten groups, through 25 one of which access could be had to the connectors containing lines numbered from 1000 to 1999, through the next, to lines numbered from 2000 to 2999, and so on. Similarly, the connector switches in each thousands group 30 would be divided into ten sub-groups according to their hundreds digit. Through the first of these sub-groups, lines numbered from 100 to 199 could be reached, through the second lines numbered from 200 to 299, 35 and so on. Obviously therefore, access could be had to any desired line by selecting first a second selector of the thousands group in which that line number occurs, and then by means of that selector picking out a connector of the hundreds group in which the 40 line number occurred. That connector would then actually contain terminals of the wanted lines. Of course in practice the wiring between the different groups of switches 45 is quite complicated because of the large number of trunk wires employed to furnish the various combinations required between the switches, but the theory is quite simple, and is well enough illustrated in Fig. 1.

50 As soon as one of the subscribers at the left of Fig. 1 has become connected in the manner stated with one of the subscribers at the right, it is unnecessary and in fact undesirable for the operator to remain longer 55 in connection with them, and means are provided for automatically cutting off and restoring the secondary selector switch as soon as this condition is brought about. Thereafter all the switches in use between the two 60 subscribers are under their own control, and when they finally hang up their receivers the several switches are automatically restored, the connection is broken, and all 65 parts resume the positions of idleness, diagrammatically illustrated in Fig. 1.

It will be noted after reading the foregoing, that portions of the apparatus and circuits at the central office are common to all or a number of subscribers' lines, whereby confusion might arise from simultaneous 70 connection of more than one line to the same trunk, more than one trunk to the same line, more than one trunk to the same operator, or more than one operator to the same trunk. Special provision is made however, to prevent this. At the left of Fig. 1 I have indicated what I call a primary distributing switch and a secondary distributing switch. The first of these contains in its banks testing terminals of the primary switches or 80 first selector trunks. It is actuated in response to the subscribers' calls, and always acts to select and start up an idle switch and trunk for connection with the calling line. There is only one distributing switch for all 85 the primary selector switches serving the same group of subscribers, hence only one switch can be started at a time, and this prevents more than one trunk being connected to the same line. In going to the line, the 90 action of the primary switch is to test over its bank contacts until it reaches a contact which has had its condition changed, due to current flowing in the calling line. If more than one line is calling, the switch will stop 95 at the first one to be reached, and thereafter the distributing switch will start another primary selector to search for the second calling line, whereby it is impossible for more than one line to get on the same trunk. 100

The secondary distributing switch performs the same functions with respect to the operators' or secondary selector switches, and is actuated also in response to the subscribers' calls, so as to start only one secondary selector switch at a time for any one group of trunks.

Figs. 9 to 13 inclusive show the type of unit switch used both for selectors and connectors in this system. The mounting plate 110 carries a pair of contact banks on its face. In its general structure this switch is the same as that described and claimed in my prior application filed May 17, 1910, Serial No. 561,804, containing also some features 115 described and shown in Patent No. 977,536, granted December 6, 1910, to Charles H. North. The present features of improvement to be claimed herein, relate to the grounding of the wipers and the use of an 120 additional wiper for row testing. In Fig. 9, the upper bank contains connective or talking circuit terminals, and the latter bank contains test terminals arranged in a peculiar manner. The uppermost of these 125 marked c^{28} in Fig. 9 constitute a horizontal row with flat faces laid horizontally, as best shown in Fig. 10. All the rest of the terminals indicated as c^{25} in Fig. 9 and individually in line with c^3 , c^4 in Fig. 10, are 130

arranged in ten vertical rows of ten pairs of contacts each, each row being aligned with one of the flat contacts c^{26} . Coöperating with the talking or connective terminals in the upper bank is a pair of connective wipers w^3, w^4 secured on opposite sides of an arm fixed on the spindle, and pressing with considerable tension against opposite sides of the insulated extremity of said arm. 5 By this construction, the rigid arm serves to perfectly align the wipers on the spindle, and their initial tension is transferred to the circuit terminals at the instant of contact in starting to travel up a row. Rows of 10 testing terminals c^{25} in the lower bank are aligned vertically with and correspond individually to the connective terminals in the upper bank. It should be remarked that these terminals are not visible in Fig. 10, 15 which is a plan view, and in which the flat terminals c^{26} hide those beneath them exposing only the talking terminals c^3, c^4 .

Coöperating with test terminals c^{25} is a pair of wipers w^{25} precisely similar to the 20 wipers w^3, w^4 ; but to coöperate with the row test terminals a horizontal rotary wiper w^{26} is employed, made in two parts, that is a solid bent anvil spring, secured directly to an adjustable hanger carried on the spindle; and a relatively light contact spring secured over the anvil with its extension resting thereon under tension. By this construction, the vertical adjustment of the wiper w^{26} as well as its horizontal alinement 25 is rendered positive, and the initial tension of the spring is transferred to the row test terminals c^{26} at the instant of contact.

In order to insure successful releasing of 40 all the switches in the system, I provide a forward release through a special third conductor built up of the several links in connection. To guard against separation of the links before all the switches have released, 45 I provide a latch as shown in Fig. 11, which is pivoted on the inner face of the switch frame so as to engage and hold the detent dog m^5 when it is actuated by the lever m^8 of the release magnet M^3 . In order to 50 unlatch the dog before the switch is again operated, so that the spindle will remain where it is set, I make it in a bell crank shape, with its upper arm engaging the armature lever m^5 of the rotary actuating magnet M^5 which is the first to be energized in operation.

Other features of the switch will be apparent from the statement of operation and claims hereinafter.

60 The relays throughout this system are preferably of the type shown and described in Letters Patent No. 972,634, granted October 11, 1910, to Charles H. North; but any standard relay may be adapted to this 65 service.

The operator's keys employed as shown in Fig. 6 are built in strips, are interlocking, and preferably of the general type shown in Letters Patent No. 955,134, granted April 19, 1910, to John F. Cadell; but other standard interlocking keys may be employed.

The distributing switches shown at S, S', S^2, S^3, S^{11} in Figs. 2, 5, 4, 8 and 9, are preferably of the type shown in my prior application, Serial No. 569,606 filed June 29, 1910, being single motion step by step electromagnetically driven switches with driving magnets mounted as a unit on a short frame secured to the contact bank. Each row or set of contacts in the bank is accompanied by a continuous solid return contact, bridged with the individual unit contacts by the wipers as they pass.

The subscriber's apparatus forms no part of the present invention except as it is included for completeness of description, and is of any usual or desired type.

Turning to the circuits, Fig. 2a illustrates simply the principles I employ in the distribution of calls. 5—6 are primary trunk conductors terminating on wipers w^3, w^4 of primary selector switch S^4 containing connective line terminals c^3, c^4 individual test terminals c^{25} , and row test terminals c^{26} , arranged as already explained. S is a distributing switch with two banks and two wipers w_S , the first bank connected to cut-on relays R^{13} in the several trunks, and the second bank to contacts in corresponding tip relays R^{14} in the several trunks. When subscriber A calls by closing his line circuit 1—2 at H , line relay R' is energized, and battery B is connected to three circuits; (1) that of starting relay R^4 ; (2) 25 to c^{25} ; and (3) 26 to c^{26} . R^4 closes 39 to 38 (of an idle trunk), R^{13} and ground. R^{13} energizes, connecting battery to M^5 and interrupter d^1 to ground. M^5 rotates S^4 until w^{26} touches c^{25} , designating the row containing A's terminals; R^{13} is energized through: B, 26, c^{26} , w^{26} , R^{13} to ground. M^5 is disconnected, R^{13} locks, and M^4 is connected to battery. M^6 steps up S^4 until w^{25} reaches c^{25} , whereupon R^{14} energizes through: B, 25, c^{25} , w^{25} , R^{14} , ground. M^6 and R^{14} are both cut off instantly, the bridge circuit through R^{14} and R^{15} (previously opened by R^{13}) is restored, R^{15} energizes through 6, $w^4, c^4, 4, R^2$ and ground, and R^{14} energizes through $R^{15}, 6, w^4, c^4, 4, 2, A, 1, 3, c^1, w^3, 5, R^{14}$, ground. Circuit 178 of release magnet M^3 is opened having previously been closed to ground when the switch started, but held open at another point by R^{13} . R^{14} puts battery on the second or test bank of R^5 energizing its relay, connecting battery to stepping magnet M , and kicking the switch forward until an idle trunk, with relay R^{14} deenergized, is found.

When A hangs up, R^{14} deenergizes, and M^3 takes current through B contacts of R^{18} and R^{14} , 178, M^3 , and ground.

The same principle of selection here exemplified is applied to the secondary selector switch by which the operator gains access to the link 5—6, and the calling line 1—2. The starting relay and secondary distributing switch as well as the test contacts in the secondary selector switch are controlled preferably through the cut-on relay R^{13} in the primary trunk selected; but they may be controlled in part from the primary distributing switch and the line, since the identity of the group of trunks is known when the identity of the corresponding group of lines is known, and of course a call over any line at once identifies each group by energizing its primary selector.

Bearing in mind now the general principles of selection shown in brief in Fig. 2^a the system may be readily comprehended in its entirety. For the sake of clarity and simplicity details were omitted altogether from Fig. 2^a, and furthermore slight variations of the circuit arrangements were made.

Referring now to Fig. 2, and bearing in mind also the general description of Fig. 1, each line circuit 1—2 is provided with a line relay R' and a cut-off relay R^2 which when energized disconnects the line relay R' and connects the tip and sleeve sides of the line to its multiple bank contacts in the primary and connector switches of its group. The attraction of the armature r^{12} of the relay R' connects ground to the individual test contacts of the primary switches S^1 .

The attraction of armature r^{12} locks the relay R' on short circuit to ground through armature r^{23} of relay R^2 , which prevents interference by the subscriber in case he should move his receiver hook.

The line relays R' are divided into groups of ten and the windings of each group are connected in multiple to the winding of a relay common to the group, which when energized connects ground to the row contact of the primary switch through the armature r^{31} , thus designating the group of lines calling, while the relay R' designates the particular line in the group.

Each group of one hundred lines is assumed to have access for calling purposes to ten primary selector trunks, such as shown in Fig. 3, and to be accessible for calling through ten connector switches such as shown in Fig. 4. Thus, each line has twenty sets of multiple contacts, ten in primary selector banks, and ten in the connector banks.

The primary distributing switch S determines which trunk in the group of ten being idle shall respond to any particular call in its group of lines; and one of these primary distributing switches is therefore required

for each group of one hundred lines, with 65 its ten trunks. Associated with each primary distributing switch S there is a secondary distributing switch S^2 , and a kick-off switch S' . The function of the secondary distributing switch is to pick out an idle 70 operator's circuit and start the same to testing for the group of primary trunks over which the call originates. This can be done because there being only one switch S^2 for each group of one hundred lines, that is to 75 say for each group of ten trunks such as shown in Fig. 3, and since it is convenient to arrange the contacts of each group of ten trunks in one and the same row in the secondary selector switches S^s (Fig. 5), each 80 secondary distributing switch can therefore be directly identified with its own associated row of primary trunk contacts in each of the secondary selector switches. Furthermore, 85 since each secondary distributing switch S^2 has a number of contacts in its banks, these contacts may be individually connected to several secondary switches, the use of multiples for this purpose in the switches S^2 being thereby avoided, and a great additional advantage gained, in that simultaneous calls may be distributed from different groups such as shown in Fig. 2 to different operator's circuits such as shown in Fig. 5 without interference even when the 90 calls are absolutely simultaneous. The circuits by which this result is attained are shown in Fig. 8 stripped of the detail of the other figures. Assuming an exchange of one thousand lines in which there would 100 be ten groups of lines and trunks, with one secondary distributing switch S^2 for each group, corresponding contacts s^2 and s^{20} are multiplied in the ten switches and connected respectively to wires 221 and 79 leading to the various secondary switches S^s .

The contacts s^{20} are not multiplied but are wired direct to the row contacts s^{32} of the secondary switches S^s . Number one switch S^2 belonging to a certain group has 110 its first contact s^{20} wired to number one row contact of the first secondary switch S^s , its second contact s^{20} wired to number one row contact of the second secondary switch S^s , and so on.

Number two switch S^2 belonging to another group has its first contact s^{20} wired to number two row contact of the first secondary switch S^s , its second contact s^{20} wired to number two row contact of the 120 second secondary switch S^s , and so on.

In an exchange of one thousand lines the contacts s^{20} of the tenth switch S^2 are wired to number ten row contacts of the secondary switches S^s .

If in an exchange of one thousand lines simultaneous calls should come in from each group of one hundred lines and ten second-

ary selector switches S^8 were provided, one row contact in each switch S^8 would be made active.

Without any confusion each switch S^8 5 would test for its active row contact and then find the individual contact in the row. The individual test contacts would be multiplied in a group of secondary switches S^8 so that any switch S^8 in the group can pick 10 out any trunk belonging to its group.

The relay R^5 has one terminal of its winding connected to the wiper arm w^8 of the switch S . When the arm w^8 in rotating finds an idle primary switch S^4 the relay R^5 15 is energized in series with the relay R^{13} (Fig. 3) and opens the circuit of stepping magnet M , thus bringing the switch S to rest. The energizing circuit of relays R^5 and R^{13} may be traced battery B (Fig. 3), 20 34, 35, 36, r^{151} , R^{13} , 38 (38 Fig. 2), 8, ws , 39, R^5 , 40, r^{42} , to ground. The energizing of the relay R^5 causes the switch S^2 to immediately start to pick out an idle secondary switch S^8 . The switch S^4 can be testing for the 25 calling line while the switch S^8 is testing for the trunk shown in Fig. 3.

The relay R^{13} acts somewhat as the line relay R' , connecting battery to its individual test contacts in the switches S^8 .

30 It will be noticed in the statement of operation hereinafter that the relay R^{13} is not deenergized until the primary switch finds the calling line and the secondary switch S^8 finds the trunk connected to that line. 35 By this arrangement all confusion is avoided regardless of which switch performs its functions first.

Referring to Fig. 3, the relay R^{12} is the 40 row test relay, and is energized when the wiper w^{26} finds an active contact, disconnects rotary relay R^{18} and in its place connects vertical relay R^{19} .

The relay R^{15} is used in testing for the 45 individual contact as well as a battery supply relay for the calling subscriber. When energized this relay disconnects the row relay R^{12} . The deenergizing of relay R^{12} disconnects the relay R^{15} from the test wiper w^{25} and connects it to the sleeve wiper w^4 50 in series with the cut-off relay R^2 .

Relay R^{14} is the tip battery supply relay and controls the release magnets M^3 and M^4 after the first selector switch S^5 has moved off-normal. The relay R^{42} is used for opening the talking circuit while the impulses 55 are being sent to operate the outgoing switches. This relay also with R^{16} jointly controls the relay R^{13} . Relay R^{41} is the test relay having its locking contact r^{413} connected to the test wiper w^{147} . Its circuit is initially closed through the contacts of relay R^{42} and foot springs 144 and 145. After the switch S^5 makes its first vertical step the circuit of this relay is maintained 65 through contacts of relay R^{42} and test wiper

w^{147} so long as this wiper encounters busy contacts which are grounded through other switches.

Referring now to Fig. 4, relays R^{22} and R^{23} respond to impulses from the sending 70 machine.

Relay R^{23} receives the first set of impulses belonging to the connector and causes the stepping magnet M^{11} of the auxiliary switch S^7 to step around so as to pick out generator current of the proper character. 75

Operation of relay R^{23} closes the circuit of relay R^{24} whose locking contact r^{241} is connected to the bottom contact of relay R^{22} . Relay R^{23} also closes circuit of relay R^{27} . This latter remains energized until the called party answers or until the calling party hangs up his receiver. 80

In case the called-for line is busy, relay R^{27} will be deenergized by action of test 85 relay R^{29} . Relays R^{24} , R^{27} and R^{29} all have their circuits completed to ground side of battery through test wire 200, contacts c^{200} , w^{147} , 147 r^{413} to ground.

When the calling party hangs up his receiver after failing to get his party, switches S^4 and S^5 are restored and ground removed from test wire, causing deenergization of 90 any of the relays R^{24} , R^{27} or R^{29} which happen to be locked.

95 The switch S^7 is restored to normal after the called subscriber hangs up his receiver or when the relays R^{25} , R^{27} and R^{24} are deenergized; and just before it reaches its normal position the wiper arm w^{87} passes over a contact and closes the circuit of the release magnet M^{12} restoring the connector switch S^6 to normal position. Thus the connector switch S^6 has a quick release if the called-for line is busy, and after the 100 called party answers a slow release by switch S^7 which takes care of any accidental shaking of the receiver hook when the called party answers.

Referring to Fig. 5 relay R^{31} is the row 110 test relay and R^{30} the individual test relay. Relay R^{32} is the control relay and corresponds to relay R^{13} (Fig. 3). Relay R^{34} is the signal relay and pulls up in series with relay R^{42} (Fig. 3) after the primary trunk 115 has found the line and the secondary switch S^8 has found the trunk. The operation of this relay closes the circuits of the signal lamp L^8 (Fig. 6), the guard lamp L^2 and the night alarm bell. Relay R^{33} is the listening 120 relay actuated by listening key LK. Operation of this relay deenergizes relays R^{34} and R^{42} and closes circuit of listening lamp L^4 . Relay R^{36} is the starting relay and is energized in series with R^{42} by the key SK. 125 This relay disconnects relay R^{33} and connects the starting cam on the sending machine to stepping magnet M^{16} . It also closes circuit of guard lamp L^2 and disconnects battery from the first five contacts over 130

which wiper ws^{300} sweeps. After arm ws^{300} passes the fifth contact it encounters battery potential and relay R^{35} is energized and connects interrupter I to magnet M^{15} until arm ws^{300} reaches its normal position.

5 Just before switch S^3 reaches normal position, cam springs 167, 168 are closed, completing the circuit of release magnet M^{16} , restoring switch S^8 to its normal position.

10 Relay R^{37} is the trunk start relay and is also used for release in case the calling subscriber has hung up his receiver or if the operator fails to get a response after pressing the listening key.

15 This relay R^{37} is energized by key RK, which also actuates relay R^{36} . These two relays being energized at the same time remove battery connection from the first two contacts over which arm ws^{300} sweeps. In 20 trunk calls, such as to wire chief, toll board, etc., it is only necessary to operate the first selector switch, which with the present sending machine requires only two rotations of the drum. The trunks of this class are wired 25 directly to certain bank contacts of the first selector switches and not to the connector banks, for quick trunk service. After arm ws^{300} passes the second contact the relay R^{35} is energized and operates as before.

30 In case the calling party hangs up his receiver before the operator answers, relay R^{38} is energized in series with resistance coil r when the operator presses the listening key, which connects the tone test to the 35 operator's telephone set, whereupon she presses the trunk start button RK.

The first selector switch S^5 upon receiving the first rotary impulse from the sending machine through one of the buttons of 40 the strip K' closes the foot springs 175 and 176. The closure of these springs while relay R^{14} is deenergized completes the circuit of release magnets M^3 and M^4 causing the 45 release of switches S^4 and S^5 . Switch S^4 in restoring disconnects relay R^{15} which opens circuits of relays R^{42} , R^{36} and R^{37} . Relays R^{36} and R^{37} falling back connect battery to contacts $1s^{300}$ to $5s^{300}$, energizing 50 relay R^{35} to restore switch S^8 and S^5 . At any time during the building up of a connection the switches can be restored by the calling party in the manner described.

Referring to Fig. 6, number one key of 55 each strip is connected to the contact on the sending machine which transmits one impulse at each rotation; number two key to that which transmits two impulses, and so on to number ten key which transmits ten impulses. Each strip of keys has a 60 common wire connected to one contact of each key in the strip and leading to its proper contact in the banks of the switch S^3 . The order in which these are arranged to transmit impulses in proper sequence is 65 as follows: At the first rotation of the send-

ing machine the first strip of keys (hundreds) is connected to the tip side of the trunk through switch arm ws^3 and contact $1s^3$; second rotation, ten test impulses from disk D^{12} sent to sleeve side of trunk through 70 arm ws^{30} and contact $2s^{30}$; third rotation, selective ringing strip K^2 connected to tip side of trunk through arm ws^3 and contact $3s^3$; fourth rotation, keys K^2 (tens) connected to sleeve side through wiper ws^{30} and 75 contact $4s^{30}$; fifth rotation, keys K^2 (units) connected to tip side of trunk through arm ws^3 ; during the fifth rotation and just after the units impulses have been set, a single test impulse is sent to sleeve side of trunk 80 through disk D^{12} , wiper ws^{30} and contact $5s^{30}$; sixth rotation, arm ws^{300} engages contacts connected to battery energizing relay R^{35} . This relay unlocks R^{36} , restores switches S^4 and S^5 , thus disconnecting secondary switch S^8 from the primary trunk 85 in Fig. 3.

The kick-off switch S' in Fig. 2 is provided for the purpose of preventing a defective trunk or operator's circuit from remaining connected to the calling line. In a word, it is a time controlled element started when a call comes in and operating after a predetermined interval longer than the time required for full operation of the switches 90 S^4 and S^5 in Figs. 3 and 5 respectively, so that if the connection from the line in Fig. 2 through Fig. 3 into Fig. 5 is not complete, the switches are restored.

The wipers ws^3 and ws^{10} are swept over 100 their bank contacts by stepping magnet M' , operated once at each rotation of the sending machine drum by closure of contacts d^{11} . The bank contacts are multiplied as shown, three contacts being left blank in 105 each bank. The multiple contacts over which the wiper ws^3 sweeps are arranged one step in advance of the corresponding contacts over which wiper ws^{10} sweeps. Relay R^9 is energized when switch S^2 picks out 110 a secondary switch S^8 and partly closes circuit of magnet M' . When the cam on the sending machine closes springs d^{11} the circuit is completed and switch S' moves one step at each rotation of the sending machine. 115 The maximum time for the secondary switch S^8 to pick out the trunk terminating on the tenth contact in the tenth row would permit about two rotations of the sending machine. As shown by the blank contacts in 120 S' the minimum time element for three rotations has been allowed and the maximum for six, depending upon the position of the wipers of switch S' when relay R^9 is energized.

If wiper ws^{10} has just passed multiplied contacts $1s^{10}$ it will then require three steps of switch S' before wiper ws^{10} finds battery potential to energize relay R^7 . In this case it would require three more steps for wiper 130

- ws' to complete the circuit of relay R⁶. If wiper ws¹⁰ is resting on multiplied contact 1_{s¹⁰} when relay R⁹ is energized, it will require only three steps of wiper ws' before the circuit of the relay R⁶ is closed. When relay R⁶ operates it places ground on 218, 219, r⁵¹, 31, M to battery, operating magnet M to step wiper ws to the next contact and thereby unlock the relay R⁵ which in turn deenergizes relays R¹¹, R⁹ and R⁸. The operation of relay R⁶ also places ground on 218, 220, ws², 221, r⁵⁴ (Fig. 5), 122, 171, through release magnet M¹⁶ to battery, causing the release of secondary switch S⁸.
- 10 If for any reason the secondary switch after it is selected fails to make proper connection with the trunk in Fig. 3 so as to relieve relays R¹³ and R⁵, the kick-off switch will come into play and between three and 20 six rotations of the sending machine cause secondary switch S⁸ to be released and the switch S to pick out another trunk.
- 15 A second bank and wiper are shown in switch S in dotted lines, Fig. 2, to indicate the same method of connection, control and release for the primary switches (Fig. 3) by switch S'. The employment of this feature is optional, as in practice if switch S⁴ is left off normal lamp L⁸ quickly attracts 25 attention thereto and localizes the trouble.

Operation.

- The subscriber at station A desiring a connection lifts receiver R from hook H which 30 bridges his telephone across line wires 1—2, energizing relays R¹ and R³ by way of B, 19, 20, R², 21, R', 22 r²¹, 1, station A, 2, r²², 23, ground to battery. Relay R' locks to ground through r²¹, 24, and r²³, and connects 35 ground to individual test contact c²⁵ through 25 and r²², while R³ connects ground to row test contact c²⁶ through 26 and r²¹ and completes circuit of group lamp L and relay R⁴, the former from B, 19, 27, L, 28, r³², ground 40 to battery; the latter from B, 19, 29, R⁴, 30, r³³, to ground. Lamp L lights, and relay R⁴ completes circuit of stepping magnet M to 45 interrupter I for intermittent energization over the path, B, 19, M, 31, r⁵¹, 32, r⁴¹, 33, 50 I to ground. Magnet M moves switch S step by step until wiper ws engages a contact s connected to relay R¹³ (Fig. 3) of an idle primary selector trunk, whereupon relays R⁵ and R¹³, (Figs. 2 and 3) are energized by current through B, (Fig. 3), 34, 35, 36, r⁵¹, 37, R¹³, 38, (38 Fig. 2), s, ws, 39, R⁵, 40, r⁴², to ground. Relay R⁵ opens circuit of magnet M at r⁵¹, locks itself to ground through r⁵² and completes circuit of 60 R¹¹ over path B, 19, 41, R¹¹, 42, r⁵³ and ground. Relay R¹¹ locks itself to battery through r¹³¹, 43, r⁴²¹, 44, and 34 to B; connects battery to one terminal of relay R¹², through 34, 35, r¹³², 45, 46, r¹⁵², 47, and 48; 65 and also completes circuit of rotary relay

R¹⁸ through r¹³² and interrupter I, so that this relay is energized intermittently, its circuit being; B, 34, 35, r¹³³, 45, 46, r¹⁵², 47, 49, 50, R¹⁸, 51, r¹²¹, 52, r¹³², I to ground. At each actuation of relay R¹⁸ magnet M⁵ is energized by current from B, 34, 57, contacts 70 58 of foot step switch F⁴, 59, M⁵, 53, r¹⁵¹, ground, stepping primary selector switch S⁴ around until wiper w²⁶ engages row test contact c²⁶ whereupon relay R¹² is energized over circuit B (Fig. 3), 34, 35, r¹³³, 45, 46, r¹⁵², 47, 48, R¹², 49, w²⁶, c²⁶, (Fig. 2) 26, r⁵¹, ground to battery. Relay R¹² locks itself to ground through r¹²², connects test wiper w²⁵ to sleeve relay R¹⁵ through 54, r¹²³ and 75 55, and shifts interrupter I from rotary relay R¹⁸ to vertical relay R¹⁹ at r¹²¹, so that R¹⁹ is intermittently energized over the circuit: B, 34, 35, r¹³³, 45, 46, r¹⁵², 47, 49, R¹⁹, 56, r¹²¹, 52, r¹³², I, ground, to battery. At 80 each actuation of relay R¹⁹ vertical magnet M⁶ is energized over the path B, 34, 60, M⁶, 61, r¹⁹¹ to ground, stepping switch S⁴ up until wiper w²⁵ engages individual test contact c²⁵ (Fig. 2) whereupon sleeve relay R¹⁵ is energized over the circuit: B, (Fig. 3), 34, 35, 62, R¹⁵, 55, r¹²³, 54, w²⁵, c²⁵, (Fig. 2), 25, r¹² (of relay R'), ground to battery. Relay R¹⁵ connects battery to trunk conductor 7, by way of r¹⁵¹, 63, 64, r¹⁴¹, 65, and resistance r, and at the same time opens the circuit of relay R¹² at r¹⁵². Relay R¹² opens 85 circuit of vertical relay R¹⁹ and magnet M⁶ is deenergized, which permits wiper w²⁵ to stop on contact c²⁵, wipers w³ and w⁴ engaging contacts c³ and c⁴, respectively. Tip relay R¹⁴ is now energized through subscriber's telephone in series with R¹⁵. Simultaneously with the selection of the calling line as described, distributing switch 90 S², (Fig. 2) is stepped around in search of an idle secondary selector, by magnet M² in circuit: B, 19, 41, 66, 67, 68, r⁹¹, 69, M², 70, r¹¹¹, 71 I to ground. Switch S² continues to step around until wiper arm ws²⁰⁰ engages 100 a contact s²⁰⁰ connected to an idle secondary selector, whereupon relays R¹⁰ and R³², (Figs. 2 and 5) are energized in series, the circuit being: B, (Fig. 5), 86, springs 73—74 of operator's jack J, 75, springs 76—77 of 105 foot step switch F, 78, R³², 79, through Fig. 3 into Fig. 2, s²⁰⁰, ws²⁰⁰, 80, 81, R¹⁰, 82, r¹¹² to ground. The actuation of relay R¹⁰ causes the energization of relay R⁹, the circuit being: B, 19, 41, 66, 67, r¹⁰¹, 83, 84, R⁹, 85, 110 r¹¹³ to ground. Relay R⁹ locks itself to battery through r⁹², and opens circuit of magnet M² at r⁹¹, whereupon switch S² comes to rest with wiper arms ws², ws²⁰ and ws²⁰⁰ resting 115 on contacts s², s²⁰, and s²⁰⁰, respectively. The attraction of armature r⁹¹ of relay R⁹ connects battery to wire 99 which completes part of the row test circuit and the attraction of armature r⁹² completes the circuit of relay R⁹ as follows: B, to R⁸, 223, 120 130

r^{93} to ground. Relay R^8 , ground wire 80, shunting relay R^{10} out of series with relay R^{32} (Fig. 5) the circuit of the latter relay now going direct to ground by way of wire 80 and armature r^{82} . Relay R^{32} (Fig. 5) completes the circuit of rotary relay R^{30} through interrupter I so that said relay is intermittently energized by current over B, 86, 87, r^{301} , 88, r^{311} , 89, R^{30} , 90, r^{321} , I to ground. Relay R^{32} also connects one terminal of relay R^{30} to ground through 91 and r^{322} , and locks itself to battery through 92, r^{323} , 93, r^{302} , 87, 86, B. Each actuation of relay R^{30} energizes rotary magnet M^{13} through B, 86, 94, M^{13} , 95, r^{311} to ground. Magnet M^{13} steps switch S^8 around until wiper w^{82} engages contact s^{82} . The first rotary step of the switch S^8 disconnects contacts 76 and 77 of switch F^8 and connects contacts 76 and 290, which opens the initial energizing circuit of relay R^{32} , (that relay, however, remaining energized through its locking circuit) and closes the circuit of off-normal lamp L^7 as follows: B, 86, 73, 74, 75, 76, 290, L^7 to ground. When wiper w^{82} engages contact s^{82} the relay R^{31} is energized over the path: B, ground to r^{322} (of relay R^{32}), 91, 96, R^{31} , 97, w^{82} , s^{82} , 98, through Fig. 3 into Fig. 2, s^{20} (in switch S^2), w^{82} , 99, r^{311} , 68, 67, 66, 41, 19, battery. Relay R^{31} locks itself to battery through: 100, r^{312} , 101, 88, r^{301} , 87 and 86, opens circuit of relay R^{30} and closes circuit of relay R^{40} at r^{311} . Relay R^{30} opens circuit of magnet M^{13} at r^{301} which stops switch S^8 with wiper w^{82} engaging contact s^{82} . As circuit of relay R^{40} is completed at r^{311} said relay is intermittently energized through: B, 86, 87, r^{301} , 38, r^{311} , 102, R^{40} , 103, 90, r^{321} , I, ground. Each actuation of relay R^{40} energizes vertical magnet M^{14} through: B, 86, M^{14} , 104, r^{401} , ground. Magnet M^{14} steps switch S^8 up until wiper w^{84} engages contact s^{84} , whereupon relay R^{30} is energized through: B, ground to r^{322} (relay R^{32}), 91, R^{30} , 105, w^{84} , s^{84} , 45, (45 Fig. 3), r^{132} , 35, 34, battery. Relay R^{30} opens locking circuit of relay R^{32} at r^{302} , also opens circuit of relay R^{40} at r^{301} . r^{401} of relay R^{40} opens the circuit of vertical magnet M^{14} which stops switch S^8 with wipers w^{80} , w^{81} , w^{83} , and w^{84} on contacts s^{80} , s^{81} , s^{83} and s^{84} . (Wiper w^{82} is raised off row contacts by first step.) Wiper w^{82} engaging contact s^{82} , (Fig. 5) relays R^{34} and R^{42} , (Figs. 5 and 3) are energized through: B, (Fig. 3), 34, 35, 36, r^{151} , 63, 106, R^{42} , 107, (107 Fig. 5), s^{88} , w^{82} , 108, r^{313} , 109, r^{351} , 111, 112, R^{42} , 113, r^{331} , 114, r^{361} , 115, r^{352} , 116, r^{322} , ground. Relay R^{42} , when actuated, opens series circuit of relays R^5 and R^{13} (Figs. 2 and 3) at r^{421} . Relay R^{13} disconnects interrupter I at r^{132} and relay R^5 (Fig. 2) opens circuit of relay R^{11} at r^{53} . Relay R^{11} deenergizing opens circuits of magnet M^2 , relay R^9 and relay R^{10} , while relay R^8 , its circuit opened at r^{93} , opens circuit of stepping magnet M' at r^{81} . This prepares distributing switches, S and S^2 , with their relays, for another call. Relay R^{34} becoming energized 70 closes circuit of night alarm N through: B, 86, 110, 117, 118, r^{341} , 119, N, to ground; closes circuit of guard lamp L^2 (Fig. 6) through B (Fig. 5), 86, 110, 117, 118, r^{342} , 120, 121, (121 Fig. 6), L^2 to ground; closes 75 circuits of service meter E (Fig. 5) through B, armature r^{343} , 122, 242, and magnet of service meter E to ground; and line lamp L^3 (Fig. 6) through B (Fig. 5) r^{343} , 122, 123, (123 Fig. 6), L^3 to ground. The operator, perceiving the signal, depresses listening key LK (Fig. 6) energizing listening relay R^{33} (Fig. 5) through: B, (Fig. 5), 86, 87, r^{301} , 88, 101, r^{312} , 124, R^{33} , 125, (125 Fig. 6), contacts of key LK, 126 to ground. Relay R^{33} energizing, opens series circuit of relays R^{34} and R^{42} at r^{331} and locks itself to ground through r^{331} , and 114, as previously traced. Relay R^{42} deenergizing, opens circuit of relay R^{11} at r^{421} . Relay R^{33} completes the operator's listening circuit as follows: receiver OR, 127, tip p , spring j , 128, r^{332} , 129, 131, w^{80} , s^{80} , 130, (130 Fig. 3), r^{411} , 133, 9, r^{422} , 7, condenser C' , 5, w^3 , c^3 , (Fig. 2), 3, r^{21} , line wire 1, subscriber's telephone, line wire 2, r^{22} , 291, 4, c^4 , w^4 , (Fig. 3), 6, condenser C^2 , 8, r^{423} , 10, 134, r^{412} , 135, (135 Fig. 5), s^{81} , w^{81} , 132, 136, r^{332} , 137, coil 95 IC, 138, jack spring j' , plug sleeve p' , 139, receiver OR. 100

Should the calling subscriber hang up his receiver before the operator is connected, tip relay R^{14} (Fig. 3) is deenergized, its circuit being open at the subscriber's switch hook contact, and sleeve relay R^{15} remaining energized in series with cut-off relay R^2 (Fig. 2), energizing circuit of relay R^{38} , (Fig. 5) is completed as follows: B, (Fig. 3) 34, 35, 36, r^{151} , 63, 64, r^{141} , 65, through resistance r , trunk conductor 7, r^{122} , 9, 133, 110 r^{411} , 130 (130 Fig. 5), s^{80} , w^{80} , 131, 129, r^{333} , 128, 154, R^{38} to ground. Relay R^{38} energizing, connects operator's tone-test circuit Tt through 155 and 137 to operator's receiver, and the operator being thus notified that the calling subscriber has disconnected, actuates the "release and trunk start" key RK, (Fig. 6) whereupon relay R^{37} (Fig. 5) receives current through: B, 86, 110, 156, R^{37} , 157, (157 Fig. 6) key RK to 105 ground. R^{37} then energizes starting relay R^{36} in series with relay R^{42} (Fig. 3), through: B, (Fig. 3), 34, 35, 36, r^{151} , 63, 106, R^{42} , 107, (107 Fig. 5), s^{88} , w^{82} , 108 r^{313} , 109, r^{351} , 111, 141, R^{36} , 140, 158, r^{371} , 159, 157 to 115 ground through RK. Relay R^{42} energizes relay R^{41} which through armatures r^{411} and r^{412} connects impulse sending wires 130 and 135 to tip and sleeve conductors 9 and, 10 respectively. The circuit of relay R^{41} is: B, 130 120

34, 44, r^{421} , 142, R^{41} , 143, contacts 144 and 145 of foot-step switch F^s to ground. Relay R^{38} being energized, opens the locking circuit of listening relay R^{33} at r^{361} and locks itself 5 through 148, r^{361} , 115, r^{352} , 116, r^{322} , to ground; and also establishes a locking circuit for relay R^{37} through 159, r^{371} , 158, 140, 148, r^{361} to ground over the same path traced for locking circuit of relay R^{36} . Armature 10 r^{362} closes circuit of guard lamp L^2 (Fig. 6) through: B, (Fig. 5) 86, 110, 117, 149, r^{362} , 150, 121, L^2 to ground, and armature r^{363} partially closes circuit of magnet M^{15} so that when cam disk D^{11} (Fig. 6) closes contacts 15 d^{11} , said magnet is momentarily energized, stepping switch S^3 forward one step. The circuit of magnet M^{15} is: B, (Fig. 5), 86, 110, 117, M^{15} , 153, r^{363} , 152, r^{363} , starting wire 151, (151 Fig. 6), contacts d^{11} , to 20 ground.

Immediately after switch arm ws^3 engages contact $1s^3$, a number of ground impulses come from the sending machine over wire 173 (as hereinafter described) by way of 25 contact $1s^3$, wiper-arm ws^3 , trunk-conductor 131, ws^{30} , s^{30} , 130, (130 Fig. 3), r^{411} , 174, relay R^{21} to battery and ground. Each actuation of relay R^{21} closes circuit of magnet M^s at r^{211} , which steps the switch S^s forward one 30 step, springs 175 and 176 of switch F^s being closed at the first rotary step. The closure of springs 175 and 176 energizes release magnets M^s and M^t of the primary and first selector switches S^t and S^s , through 35 106, 177, r^{412} , 178, 179, M^s and M^t in multiple. B. These magnets restore their respective switches to normal position. The circuit of sleeve relay R^{15} is now open at w^4 , and its armature r^{151} opens the series circuit of relay R^{42} , and R^{36} (Figs. 3 and 5). Relay 40 R^{36} opens at r^{361} the locking circuit of relay R^{37} . As wiper arm ws^{300} is resting on contact $1s^{300}$ and armature r^{362} of relay R^{36} is retracted, the retraction of armature r^{372} , 45 of relay R^{37} , closes circuit of relay R^{35} as follows: B, 86, 110, 117, 149, r^{362} , 163, 161, r^{372} , 293, $1s^{300}$, ws^{300} , 164, R^{35} to ground. Armature r^{363} of relay R^{36} connects one 50 terminal of stepping magnet M^{15} to interrupter I for intermittent energization over the path: B, 86, 110, 117, M^{15} , 153, r^{355} , 165, I, to ground. Magnet M^{15} steps around switch arms ws^8 , ws^{30} and ws^{300} over their respective bank contacts. After wiper arm 55 ws^{300} leaves contact $2s^{300}$ and sweeps over contacts $3s^{300}$ to $5s^{300}$ relay R^{35} is kept energized through B, 86, 110, 117, 149, r^{362} , 163, 162, contacts $3s^{300}$ to $5s^{300}$, ws^{300} and so on as previously traced. When wiper arm ws^{300} reaches 60 contact $6s^{300}$ the circuit of relay R^{35} is again changed and said relay is energized while the arm sweeps over contacts $6s^{300}$ to $9s^{300}$, through: B, 86, 110, 166, $6s^{300}$ to $9s^{300}$, ws^{300} , 164, and so on as previously traced. When 65 wiper arm ws^{300} passes off the last contact

$9s^{300}$ it opens the circuit of relay R^{35} , which disconnects magnet M^{15} from interrupter I at r^{353} and stops switch S^3 with its wiper arms ws^3 , ws^{30} and ws^{300} , clear of all contacts. Shortly before switch S^3 comes to normal position, contact springs 167 and 168 are momentarily closed by a cam on the switch spindle and release magnet M^{16} is energized through: B, 86, 169, 170, M^{16} , 171, 172, 167, 168, ground. Magnet M^{16} restores switch S^3 to normal position, ready for another call. 70

If the calling subscriber remains on the line, the operator, on ascertaining the number wanted sets up the same on her key set, 80 (Fig. 6,) by depressing the key in strip K^1 corresponding to the first digit, that in the strip K^2 corresponding to the second digit, that in the third strip K^3 corresponding to the third digit, and that in the strip K^4 corresponding to the particular ringing generator to be selected, and then actuates starting key, SK, whereupon starting relay R^{30} (Fig. 5) is energized in series with trunk cut-off relay R^{42} (Fig. 3) through: ground, 126, 90 (Fig. 6) key SK, 140, (140 Fig. 5) R^{36} , 141, 111, r^{351} , 109, r^{313} , 108, ws^3 , s^{33} , 107, (107 Fig. 3), R^{42} , 106, 63, r^{151} , 35, 34, battery to ground. Relay R^{42} opens trunk conductors 9—7 and 10—8 at r^{422} and r^{423} , and energizes 95 relay R^{41} through: B, 34, 44, r^{421} , 142, R^{41} , 143, contacts 144 and 145 of switch F^s to ground. Armatures r^{411} and r^{412} connect the impulse wires 130 and 135 to rotary and vertical relays R^{21} and R^{20} , respectively, while armature r^{413} connects conductor 147 to one terminal of relay R^{41} through contact 146. Starting relay R^{36} (Fig. 5) takes ground off relay R^{33} through 114, at r^{361} , and locks 100 itself through 148, r^{361} and 115 to ground as previously traced. Armature r^{362} maintains the circuit of the guard lamp through B, 86, 110, 117, M^{15} , 153, r^{355} , 152, r^{363} , starting wire 151, (151 Fig. 6) contact springs d^{11} , to ground; so that when cam disk D^{11} (Fig. 6) closes contacts d^{11} , said magnet is momentarily energized, stepping switch S^3 forward one step. Immediately after cam D^{11} (Fig. 6) has passed under the contacts d^{11} , the number cams D' to D^{10} inclusive, pass under their respective contact springs d' to d^{10} inclusive, the cam D' maintaining the closure of contact d' during one closure of the interrupter contact springs d^1 , the cam D^2 maintaining the closure of its contact springs d^2 during two closures of said interrupter contacts, and so on to the cam D^{10} , 115 which maintains the closure of its contact springs d^{10} during ten closures of the interrupter contact springs. During the passage 120 of the number cams under their contact 125

of the number cams under their contact 130

springs, ground impulses (corresponding in number to the first digit of the wanted line) are sent over the hundreds impulse wire 173 to the rotary relay R^{21} of the first selector switch S^5 , (Fig. 3). Assuming for example, that the number wanted is 246-3, relay R^{21} will be momentarily energized two times, through: ground, d^1 , 190, d^2 , 191, 192, 193, k^{12} of strip K^1 , 173, (173 Fig. 5) $1s^2$, ws^8 , 131, ws^9 , s^{80} , 130 (130 Fig. 3), r^{411} , 174, R^{21} , battery B to ground. Relay R^{21} intermittently energizes magnet M^8 which steps switch S^8 to the second row of contacts through which the connector containing wanted subscriber's line is accessible. At the first rotary step of switch S^8 , contact springs 175-176 are closed, completing the circuit of "off-normal" lamp L^F through B, 103, 104, L^F , 105, 106, 176, 175 to ground; 20 also partially closing the release circuit through magnets M^8 and M^4 , hereinafter described. After the number cams have passed under their respective springs cam D^{11} again closes its contacts d^{11} stepping switch S^3 around to bring its wipers into engagement with the next set of contacts. Wiper arms ws^3 , ws^{30} and ws^{300} of switch S^3 now engage their respective contacts $2s^3$, $2s^{30}$, and $2s^{300}$, and cam D^{12} (Fig. 6) connects test impulse wire 189 through springs d^{12} , conductor 190 and springs d^1 to ground during ten closures of springs d^1 , whereupon vertical relay R^{20} (Fig. 3) is intermittently energized through: ground, d^1 , 190, d^{12} , 189, (189 Fig. 5), $2s^{20}$, ground, ws^{80} , 132, ws^8 , s^{81} , 135, (135 Fig. 3), r^{412} , 199, R^{20} , 196, battery, to ground. Relay R^{20} intermittently closes circuit of magnet M^1 at r^{201} , stepping up wipers w^9 , w^{10} and w^{147} of the first selector switch S^6 to engage contacts c^{13} , c^{14} and c^{200} , respectively, leading to a connector trunk (Fig. 4). At the first vertical movement of the spindle of switch S^6 the circuit of relay R^{41} is opened at contact springs 144 and 145 of switch F^5 , and should 45 the connector trunk (Fig. 4) be busy because of the wipers of another first selector switch resting on the multiples of contacts c^{200} , relay R^{41} would remain energized through B (Fig. 3), 34, 44, r^{421} , 142, R^{41} , 146, r^{413} , 147, w^{147} , c^{200} (Fig. 4) to the multiples of c^{200} and thence through the circuit of the other first selector by way of its wiper w^{147} (as in Fig. 3), 147, r^{413} , ground, to battery. The armature r^{412} of relay R^{41} , remaining attracted permits the next test impulse to energize vertical relay R^{20} stepping the wipers up to the next set of contacts, and so on until an idle connector is reached, when, relay R^{41} being deprived of ground, releases its armatures. The armature r^{412} disconnects impulse wire 135 from the relay R^{20} , stopping switch S^6 with its wipers w^9 , w^{10} and w^{147} on contacts c^{13} , c^{14} and c^{200} , respectively, of the connector trunk (Fig. 4). The impulse wires 130 and 135 are now connected. 55 to the tip and sleeve conductors 9 and 10 through armatures r^{411} and r^{412} respectively, and contact c^{200} (Fig. 4) and its multiples are connected to ground through: w^{147} (Fig. 3), 147, and r^{413} . After cam D^{12} (Fig. 6) 70 has passed springs d^{12} , starting cam D^{11} again closes springs d^{11} , steps switch S^3 around to bring its wipers into engagement with the third set of contacts. Wiper arms ws^3 , ws^{30} and ws^{300} now engage contacts $3s^3$, $3s^{30}$, and $3s^{300}$, respectively. The number cams now pass under their respective contact springs for the third time and send impulses, corresponding in number to the desired ringing generator (in this case No. 3), to relay R^{23} (Fig. 4), through: ground, springs d^1 (Fig. 6), 190, d^3 , 198, 203, k^{43} , 197, (197 Fig. 5), $3s^3$, ws^3 , 131, ws^{80} , s^{80} , 130, (130 Fig. 3), r^{411} , 133, 9, w^9 , c^{13} , (Fig. 4), 16, r^{261} , 204, R^{23} , 205, B to ground. Each actuation of relay R^{23} energizes magnet M^{11} of switch S^7 , through: B, 206, 208, 209, 210 and 211, 212, 213, M^{11} , 214, 215, w^{231} to ground. Magnet M^{11} moves switch S^7 forward three steps, bringing wipers ws^7 , ws^{70} and ws^{700} onto contacts $3s^7$, $3s^{70}$ and $3s^{700}$ respectively. 90 The first actuation of R^{23} energizes R^{24} and R^{27} , the first through: B, 206, 207, 205, r^{232} , 247, R^{24} , 202, 200, c^{260} , w^{147} , (Fig. 3) 147, r^{413} to ground, locking itself to battery 95 through 249, r^{241} , 250, r^{222} , 207; the second relay through: r^{232} (of relay R^{23}), 234, 230, R^{27} , 235, r^{232} , 236, 202, to ground, locking itself to battery through: 232, r^{271} , 233, r^{201} , 231. Cam D^{11} (Fig. 6), again closing contacts d^{11} moves switch S^8 one step bringing its wipers onto the fourth set of contacts. Wiper ws^{30} now engages contact $4s^{30}$ and the number cams close their respective springs and send impulses to R^{22} (Fig. 4) 105 through: ground, contacts d^1 , (Fig. 6) 190, d^4 , 225, 226, 227, k^{24} of strip K^2 , 224, (224 Fig. 5), $4s^{30}$, ws^{30} , 132, ws^8 , s^{81} , 135, (135 Fig. 3), r^{412} , 134, 10, w^9 , c^{14} , (Fig. 4) 15, r^{262} , 228, R^{22} , 229, 230, 232, r^{271} , 233, r^{201} , 231, 110 battery to ground. Each actuation of R^{22} energizes magnet M^9 through: B, 206, 208, 237, 238, 239, M^9 , 240, r^{221} , ground. Magnet M^9 moves switch S^9 forward four steps 115 bringing wipers w^{17} and w^{18} onto the fourth row of contacts, in which lie the wanted line contacts. 120 The first actuation of R^{22} opens the locking circuit of R^{24} at r^{222} . The first rotary step opens springs 210-211 and closes 210-246, which shifts battery lead 209 from M^{11} to M^{10} and lights lamp L^G by current through: B, 210, 246, 245, 264, 266, r^{283} , 248, L^G to ground. Cam D^{11} (Fig. 6) again closes contacts d^{11} and sends one impulse over wire 151, actuating switch S^8 to step its wipers onto their fifth set of contacts. After cam D^{11} has passed contacts d^{11} , the number cams again actuate their respective spring contacts sending unit impulses through 241, 125 130

(241 Fig. 5), w_8^s , w_8^s , 131 to R^{22} (Fig. 4). Each actuation of relay R^{22} energizes M^{10} , through: B, 206, 208, 209, 210, 246, 245, 244, 243, r^{222} , 215, r^{221} , to ground. Magnet M^{10} is actuated six times, stepping wipers w^{17} and w^{18} onto contacts c^{17} and c^{18} (Figs. 4 and 7 respectively).

The first actuation of relay R^{22} again energizes R^{24} through r^{223} and R^{24} locks itself and disconnects R^{25} and R^{26} from wipers w^{17} and w^{18} , at r^{243} and r^{241} to prevent affecting said relays while the wipers are passing over other line multiples. After the number cams pass their springs, and before cam D^{11} closes its springs, cam D^{18} closes springs d^{18} , sending a single test impulse through 292, (292 Fig. 5), w_8^{s0} , w_8^{s0} , 132, to R^{22} (Fig. 4), whereupon if the wanted line (Fig. 7) is busy, with wipers w^{17} , w^{18} , of another connector switch, or w^s , w^s of a primary selector switch, resting on multiples of contacts c^{17} , c^{18} , the test relay R^{29} (Fig. 4) is energized, in the first case through: ground, r^{113} (Fig. 3), 147, w^{147} , c^{200} (Fig. 4), 200, 201, R^{28} , 251, 252, r^{223} , 252, r^{241} , 253, 18, w^{18} , c^{18} , (Fig. 7) to the multiple of c^{18} on which the other connector switch wipers are resting, thence through that connector by way of w^{18} , 18, 253, r^{281} , 252, r^{223} , 259, R^{26} , 260, 261, r^{241} , 250, r^{222} , 207, B, 30 to ground; in the second case through: ground, R^{29} , c^{18} , thence through the multiple of c^{18} , on which wiper w^s , of a primary selector is resting, 294, r^{123} , 55, R^{15} , 62, 35, 34, B, to ground. Relay R^{29} when energized locks itself to battery through 262, r^{281} , connects the busy back B_2 to trunk conductor 16, through r^{292} and 263, and closes the release circuit of S^s through: B, 206, 208, 209, 210, 246, 245, 264, 265, r^{298} , 267, 269, M^{12} to ground. M^{12} then releases the connector switch S^s . After this impulse relay R^{22} is deenergized, and completes the restoring circuit of switch S^t , through: B, r^{222} , 250, r^{241} , 261, 270, r^{273} , 271, r^{281} , 272, 213, M^{11} , 214, r^{272} , 45 273, w_8^{s00} , w_8^{s00} , 274, I to ground.

Magnet M^{11} is intermittently energized until switch S^t reaches normal position when its circuit is opened between w_8^{s00} and s^{s00} . The test relay R^{29} remains locked, holding 50 busy-back B_2 on trunk conductor 16, to signal the calling subscriber, (Fig. 2), who then hangs up his receiver, opening circuit of R^{14} (Fig. 3) which deenergizes and releases magnets M^s and M^t of switches S^s and S^t through ground, 175, 176, 106, 177, 55 r^{142} , 178, 179, M^s and M^t , (in multiple), B, to ground. The switch S^s in restoring opens the circuit of R^{29} (Fig. 4) at c^{200} and w^{147} (Fig. 3) and the busy-back is disconnected.

60 If the wanted subscriber is not busy, R^{22} remains locked, and after the test impulse R^{22} deenergizes, which energizes R^{28} (Fig. 4) and R^{43} (Fig. 7) in series, through: B, (Fig. 4) r^{222} , 250, r^{241} , 261, 260, R^{28} , 259, r^{223} , 252, r^{281} , 65 253, 18, w^{18} , c^{18} , (Fig. 7) 255, R^{44} to ground.

Relay R^{28} closes trunk conductors 15—17 and 16—18 at r^{262} and r^{261} , respectively, while R^{43} (Fig. 7) connects line terminals 256 and 257 to extensions 254 and 255. Simultaneously with the energization of R^{28} and R^{43} , ringing relay R^{28} is connected through: B, r^{222} , 250, r^{241} , 261, 270, r^{273} , 277, r^{242} , 278, R^{28} , interrupter I^2 to ground.

Immediately after the test impulse cam D^{11} (Fig. 6) causes contacts d^{11} to send an impulse over wire 151, stepping switch S^s (Fig. 5) forward one step bringing its wipers onto the sixth contact set. When w_8^{s00} engages contact 6_8^{s00} , the restoring relay R^{25} is energized through: B, 86, 110, 166, 80 6_8^{s00} to 9_8^{s00} , w_8^{s00} , 164, R^{35} , to ground. Relay R^{25} opens circuit of R^{46} and R^{42} , (Figs. 5 and 3 respectively) at r^{351} and r^{352} , while r^{353} connects magnet M^{15} for intermittent energization through: B, 86, 110, 117, M^{15} , 85 153, r^{355} , 165, I to ground. Magnet M^{15} steps switch S^s forward, holding R^{35} energized through w_8^{s00} and contacts 6_8^{s00} to 9_8^{s00} , until the wipers have reached normal position, as shown. The secondary selector 90 switch S^s is restored by the cam on the switch S^s , in passing, and the operator's circuit is ready to receive another call.

Ringing relay R^{28} is intermittently energized by interrupter I^2 to ring subscriber 95 A^s , (Fig. 7) through circuit: G^s , 279, $3s^{70}$, w_8^{s00} , 280, r^{282} , 281, 17, w^{17} , c^{17} , (Fig. 7) 254, r^{131} , 256, 282, ringer Q^s , C^{30} , 283, 257, r^{482} , 258, 255, c^{18} , w^{18} (Fig. 4) 18, 253, r^{281} , 284, resistance r' , 285, 208, 206, B to ground 100 and generator G^s . At each energization of relay R^{28} the circuit of lamp L^s is opened at r^{288} . When the called subscriber A^s takes down his receiver, he bridges his telephone across the line, and at the next non-ringing 105 interval the circuit of the tip relay R^{25} is closed through: B, (Fig. 4) through R^{26} to c^{18} (Fig. 7), 255, r^{482} , 257, 283, H^{30} , telephone at A^s , 286, 256, r^{481} , 254, c^{17} , w^{17} (Fig. 4), 17, 281, r^{282} , 287, R^{26} , 288, r^{243} , 275, r^{221} 110 to ground. Relay R^{25} opens circuit of R^{27} at r^{252} , relay R^{27} opens circuit of ringing relay R^{28} at r^{278} , and the ringing ceases.

The calling and called subscribers A and A^s , respectively, are now connected for 115 conversation over the circuit indicated in heavy lines in Figs. 2, 3, 4 and 7.

Relay R^{28} connects test contact c^{200} through: c^{200} , 200, 202, 236, r^{252} , to ground side of battery, which renders the trunk busy 120 in case the calling party should hang up first. At the end of the conversation, when calling subscriber A hangs up his receiver the circuit of the tip relay R^{14} (Fig. 3) is opened, whereupon armature r^{142} falling 125 back, closes the circuit of release magnets M^s and M^t of the switches S^s and S^t , which return to their normal position. When called subscriber A^s hangs up his receiver, the circuit of tip relay R^{25} (Fig. 4) is 130

opened, whereupon armature r^{251} , falling back, completes the restoring circuit of switch S^7 , said switch is restored, and when wiper arm ws^7 engages contact $9s^7$ (which occurs just before the switch reaches its normal position) the circuit of release magnet M^{12} is completed as follows: battery B, 206, 207, 289, ws^7 , $9s^7$, 290, 269, M^{12} , ground, to battery. The connector switch S^6 then returns to its normal position.

The foregoing description contemplates an exchange of one thousand lines or less, in which the first selector switches are set directly to the terminals of line connectors containing hundreds groups of line terminals. In an exchange of more than one thousand lines the second selector shown in Fig. 3^a is employed, being inserted between the first selector of Fig. 3 and the connector of Fig. 4. The link conductors 371—373 and 372—374, with the third conductor 375 extending from multiple contacts c^9 , c^{10} and c^{20} in the banks of the first selector switches S^5 , to the wipers w^{130} , w^{140} , w^{200} of the second selector switch S^{10} , containing multiple contacts c^{12} , c^{14} , and c^{200} of the connector links shown in Fig. 4. M^{20} and M^{21} are rotary and vertical magnets. R^{50} and R^{51} are repeating relays therefor, M^{22} is a release magnet, and R^{52} is the test relay. The operation of this link is the same as that of the first selector, depending upon a second set of impulses from the sending machine. When switch S^5 connects with the link of Fig. 3^a, R^{52} is energized through: B, 383, R^{52} , 376, 386, 388, 377, M^{22} , 375, c^{107} , w^{147} , (Fig. 3) 147, r^{413} to ground. M^{22} is low wound, and R^{52} being high wound energizes, opening the link at r^{521} and r^{523} ; connecting 371, r^{521} , 380, R^{50} , 381, 382, 383, B; also connecting 372, 396, R^{51} , 384, normally open at 392—393, and 385 to B. Connection between S^5 and Fig. 3^a is due to ungrounded condition of wipers c^{107} , hence R^{41} is de-energized, but any unused test impulses coming over 10, w^{10} , c^{10} , 372 and 396 will not affect R^{51} or M^{21} because of open circuit.

Rotary impulses through 9, w^9 , c^9 and 371 affect R^{50} and rotary magnet M^{20} to rotate 50 spindle of S^{10} to desired hundreds row. The first rotary step closes 390—391, 392—393, cutting on R^{41} , and grounding M^{22} . Test impulses follow through 10, w^{10} , c^{10} , and 372, which start R^{51} and M^{21} to step up wiper 55 w^{200} to test for idle connector trunk in the selected group. So long as grounded or busy contacts are found, R^{52} holds up through: B, 383, R^{52} , r^{522} , 375, w^{200} , c^{200} (Fig. 4) and back through other selector 60 test wiper already in contact, as w^{200} , 375, r^{522} and ground (R^{52} in busy selector circuit being de-energized). Reaching an ungrounded terminal, R^{52} unlocks, grounding w^{200} to make contacts test busy, closing link 65 conductors, and cutting off R^{50} and R^{51} .

Release circuit with this additional selector is shown in Fig. 3^b. Release magnets M^3 and M^4 (Fig. 3) are connected in parallel to ground through 179, r^{412} , 147, w^{141} , then (Fig. 3^a) c^{197} , 197, M^{22} , 377, 390, 391 and 70 ground. In Fig. 3^b battery is connected by R^{14} through 178, r^{442} , 177, 176, 175, B. Magnets M^3 , M^4 and M^{22} are energized in parallel when the calling subscriber hangs up.

When second selectors are employed as thus described, an additional strip of keys and associated parts must be added to those shown in Fig. 6, for example by duplicating the strip K^1 . The wire therefrom, corresponding to the wires 173, 224, 241, and 197, would then be connected in its proper order to a contact on the switch S^3 (Fig. 5) and said switch adjusted to provide for the extra digits, and the corresponding extra set of test impulses required for the additional link in the building up of a connection.

Fig. 2^b shows a modification of the kick-off switch arrangement, wherein a third bank is wired up and the contacts controlling wires 218 and 218^x (Fig. 2) are connected directly to the first and third contact banks. I here dispense with relays R^6 and R^8 . Wire 80 is placed in direct control of R^6 . In Fig. 5 a cut-off relay R^{1600} is shown, which is energized through a branch of wire 164, while S^3 is restoring, to open wires 131 and 132 as indicated by crosses, and prevent transmission of stray impulses.

It will be apparent that very many changes of minor details, and modification of non-essential features, may be made in the foregoing system and apparatus, without departing from my invention. As examples, I may state that the kick-off switch S^1 might be omitted or modified, and the secondary distributing switch modified by omitting the row test connections therefrom (either the sleeve relay R^{15} or the cut-on relay R^{12} of the selected trunk being then arranged so that when energized contacts will be closed placing test potential on both the individual and row contacts in the secondary selector switch banks); the type of sending machine may be varied, using that for example shown in my prior application Serial No. 383,875, filed July 15, 1907, in which a single rotation of the drum sends all the impulses required for a complete cycle in the switch operation; and with this large sending machine, relays can be employed as shown in said application, instead of the switch S^2 in the present case. I wish it to be distinctly understood that I have described herein a complete actual commercial equipment, both in apparatus and in circuits, for the sake of certainty and clearness; and that I contemplate all such non-essential changes and modifications as fall fairly within the scope of the appended claims.

Having thus described my invention what I claim and desire to secure by Letters Patent is:

1. In a telephone exchange system, a line circuit, a line relay therefor, a source of current, automatic selective switching apparatus governed by the line relay, link circuits, means for closing the line circuit in initiating a call, to energize said relay and through it control the switching apparatus, means controlled by the relay in its actuation to maintain its own circuit complete for a flow of current directly from the source, supplementing but irrespective of the line condition, and means becoming operative upon the complete connection of a link with the line, to break both the line and direct return circuit to the battery from said line relay.
2. In a telephone exchange system, a line circuit, a line relay and a cut-off relay therefor, a direct self-locking battery circuit for the line relay extending through normally closed contacts on the cut-off relay, a primary selector switch containing contacts for the line, a link circuit associated with the switch, means responsive to the line relay for actuating the switch, a controlling relay for the switch connected to the link circuit to be energized by current therein after the cut-off relay has been energized, and a circuit for the cut-off relay of the line completed when the switch effects connection therewith, whereby the act of a calling subscriber will initially energize the line relay, said relay will start the primary selector switch and simultaneously lock itself to maintain continued action of said switch, the switch when it comes on the line contact will complete the circuit of the cut-off relay, the energization of said relay will unlock and disconnect the line relay, and the link relay, coming into connection with the subscriber's line, will thereafter control the switch in direct response to conditions in said line.
3. In a telephone exchange system, a plurality of circuits to be selected, and a testing selector switch comprising the following instrumentalities: a contact bank containing connecting terminals of the circuits arranged in a plurality of straight rows arranged parallel to each other so as to form approximately elements in the surface of the cylinder, a set of individual testing contacts associated with the connecting terminals of each row, a set of row test contacts, associated with but separate from the other terminals, each located in line with one of the rows, a spindle having its axis lying in the axis of the aforesaid cylinder, wipers on said spindle adapted to cooperate with the connecting contacts, the individual test contacts and the row test contacts respectively, an electromagnet adapted to rotate the spindle so as to sweep the row test wiper over the row test contacts, another electromagnet adapted to reciprocate the spindle so as to move the individual test and the connecting wipers over corresponding contacts in a selected row, a source of driving current for said magnets, a test relay connected to the row test wiper, an individual test relay connected to the individual test wiper, a source of driving current for said magnets, a circuit extending from said source through normally closed contacts of said row test relay to the rotary actuating magnets, a branch circuit from normally open contacts in the row test relay through normally closed contacts in the individual test relay to the reciprocating magnet, means to close said supply circuit from the source to the switch, and means to place test potential upon the row and individual contacts designating a particular circuit to be selected, whereby the switch spindle will be rotated in testing for a circuit, until the row test wiper finds the busy row test terminal, and the row test relay then becoming energized will shift the current supply circuit from

the rotary to the reciprocating magnet, the spindle will be reciprocated thereafter until the individual test wiper finds the busy individual test terminal, and the individual test relay thereupon becoming energized, will disconnect the reciprocating magnet, and bring the switch to rest with its connecting wipers resting on the connecting terminals of the desired circuit.

5. In a telephone exchange system, a plurality of circuits to be selected, and a testing selector switch comprising the following instrumentalities: a pair of contact banks, one containing straight parallel rows of connecting terminals with their inner ends forming elements in the surface of a cylinder, a second bank containing associated alined rows of individual test terminals, and a single curved set of row test terminals 15 alined with but separate from the respective rows of individual terminals, a frame secured to the banks, a spindle journaled in the frame so as to have rotary and reciprocating motion therein, with its axis coinciding with the axis of curvature of the banks, connecting and individual-test wipers carried by said spindle and adapted to coöperate in vertical motion with the straight rows of connecting and individual-test terminals respectively, a row-test wiper suitably alined with the other wipers and adapted to coöperate in rotary motion with the row test terminals, means for rotating the spindle and an electromagnet for actuating the same, means for reciprocating the spindle and an electromagnet for actuating the same, means for restoring the spindle to its initial or zero position and an electromagnet controlling the same, a row test relay connected to the row test wiper, an individual test relay for the individual test wiper, means for placing test potential on the row and individual test terminals of any desired circuit to be selected, and means for supplying actuating current to the rotary and reciprocating magnets through contacts controlled by the respective row and individual test relays, with means to supply current to the restoring means at the termination of the connection.

6. In a telephone exchange system, a plurality of circuits to be selected, and a testing selector switch comprising the following instrumentalities: a pair of contact banks, one containing straight parallel rows of connecting terminals with their inner ends forming elements in the surface of a cylinder, a second bank containing associated alined rows of individual test terminals, and a single curved set of row test terminals alined with but separate from the respective rows of individual terminals, a frame secured to the banks, a spindle journaled in the frame so as to have rotary and reciprocating motion therein, with its axis coinciding with the

axis of curvature of the banks, connecting and individual test wipers carried by said spindle and adapted to coöperate in vertical motion with the straight rows of connecting and individual test terminals respectively, a 70 row test wiper suitably alined with the other wipers and adapted to coöperate in rotary motion with the row test terminals, a rotary ratchet and a straight ratchet carried by the spindle, a pawl coöperating with the rotary ratchet and an actuating electromagnet therefor, a pawl coöperating with the straight ratchet and an actuating electromagnet therefor, a row test relay connected to the row test wiper, an individual test 75 relay connected to the individual test wiper, a source of current impulses for the actuating magnets, means for impressing a test potential on the row and individual test terminals corresponding to any desired line, 80 and circuit connections for the rotary and reciprocating magnets from said source controlled by the row test and individual test relays respectively.

7. In a telephone exchange system, line 90 circuits, primary selector switches containing connective terminals and test terminals for the lines, link circuits for the primary selectors, a secondary selector switch containing connective terminals and test terminals for the links, actuating means for said switches adapted to control the movements thereof as determined by the test, so as to identify a calling line in the primary test, and the link of the primary switch so 95 testing, in the secondary test, and starting means for both switches becoming active in response to a call over a line circuit.

8. In a telephone exchange system, line 100 circuits, primary selector switches containing connective terminals and test terminals for the lines, link circuits for the primary selectors, a secondary selector switch containing connective terminals and test terminals for the links, actuating means for said 105 switches adapted to control the movements thereof as determined by the test, to identify a calling line in the primary test, and the link of the primary switch so testing in the secondary test, and means responsive to calls 110 over the lines to start an idle primary selector testing for a calling line and the secondary selector switch testing for the selected link at the same time.

9. In a telephone exchange system, a plurality of line circuits, a plurality of link circuits for interconnecting the same, primary selector switches, one for each link, containing connective terminals and test terminals for the lines, secondary selector switches 120 containing connective terminals and test terminals for the links, a relay associated with each line and adapted to be energized when its line is calling, a primary distributing switch containing terminals for the respec- 125 130

tive links, a secondary distributing switch containing terminals for the respective secondary selector switches and their associated circuits, actuating means for the respective 5 switches, and starting circuits for the primary and secondary selector switches initially controlled through the primary and secondary distributing switches by the line relay of a calling line.

10 10. In a telephone exchange system, a plurality of line circuits, a plurality of link circuits for interconnecting the same, primary selector switches, one for each link, containing connective terminals and test terminals for the lines, secondary selector switches containing connective terminals and test terminals of the links, a relay associated with each line and adapted to be energized when its line is calling, a primary 15 distributing switch containing terminals for the respective links, a secondary distributing switch containing terminals for the respective secondary selector switches and their associated circuits, actuating 20 means for the respective switches, and starting circuits for the primary and secondary selector switches initially controlled through the primary and secondary distributing switches by the line relay of a calling line, 25 together with circuit connections for the line test contacts in the primary selector switches and controlled by said line relays, and a relay in each link controlled over the link starting circuit to close the circuit of the 30 test contacts corresponding to that link in the secondary selector switches.

11. In a telephone exchange system, a plurality of line circuits, a plurality of link circuits for interconnecting them, a primary 40 selector switch for each link containing connective and test terminals of the lines, an operator's circuit and a secondary selector switch containing connective and test terminals for the links, test wipers in both primary and secondary selector switches, and 45 means responsive to a call over any of the lines adapted to start the secondary selector switch testing to find and connect with a link, at the same time that the primary selector switch of that link is testing to find 50 and effect connection with the calling line.

12. In a telephone exchange system, line circuits, link circuits for interconnecting the same, a primary selector switch for each 55 link containing connective terminals and test terminals of the lines, a plurality of operators' circuits, a secondary selector switch for each operator's circuit containing connective terminals and test terminals for the 60 links, a primary distributing switch acting in response to current over a calling line to select an idle link and primary selector, line controlled means for imposing test potential on the test contacts corresponding to the 65 calling line in said selector, a secondary dis-

tributing switch actuated also in response to a call to select an idle operator's circuit, and a relay in each link, energized when the link is brought into service through the primary distributing switch and adapted when energized to impress test potential upon the test contacts corresponding to the link in the secondary selector switches.

13. In a telephone exchange system, line circuits, link circuits for interconnecting the same, a primary selector switch for each link containing connective terminals and test terminals for the lines, a plurality of operators' circuits, a secondary selector switch for each operator's circuit containing connective 70 terminals and test terminals for the links, a primary distributing switch having an actuating magnet acting in response to current over a calling line to select an idle link and primary selector, a secondary distributing 75 switch having an actuating magnet also acting in response to a call to select an idle operator's circuit and secondary selector, each of said distributing switches having two wipers and two banks of contacts coincidentally touched by the wipers in associated pairs, circuit controlling means associated with each of the primary selector switches and connected to one of the banks in the primary distributing switch, an electromagnet controlling the actuation of each primary selector switch correspondingly connected to the other bank in the primary distributing switch, circuit controlling means associated with each secondary selector switch and connected to one bank in the secondary distributing switch, a controlling electromagnet for each secondary distributing switch correspondingly connected to the other bank of the secondary distributing switch, and a test relay associated with each distributing switch and controlling the circuit of its actuating magnet in response to test conditions produced by the test wiper sweeping over the first bank of contacts.

14. In a telephone exchange system, line circuits, link circuits terminating in automatic switches for interconnecting the lines, an operator's circuit with switching means adapted to be connected to any of the links, a switch controlling device associated with the operator's circuit, and a cut-off relay in each link controlled by the operation of said device to sever its link for the transmission of current changes, whereby the operation of the controlling device will be confined to the automatic switches, and will be inaudible over a line already connected to the link.

15. In a telephone exchange system, line circuits, link circuits, a selective switch for each link, an operator's circuit, an impulse sender associated therewith, a cut-off relay in each link adapted to sever the link when actuated, switching means for connecting the operator's circuit to the selector switch

of any link and circuit connections for the cut-off relay of a link so connected, controlled in the use of the impulse sender.

16. In a telephone exchange system, a selector switch including trunk terminals arranged in groups, a testing wiper adapted to be driven to a predetermined group, a test relay, a circuit for said relay externally controlled on one side and branched on the other, contacts in one branch normally closed to complete the circuit when the switch spindle is in its normal or inactive position, contacts in the other branch normally open but closed when the relay is energized to complete the branch to the test wiper, means for imparting initial movement to the wiper for testing a group of terminals to which it has been driven, means controlled in the energization of the test relay to continue said movement of the latter over the group of terminals, and means for maintaining a distinctive test potential on the terminals of all trunks in use, whereby the test relay being initially energized in a circuit closed in a normal position of the switch, it will remain locked as long as the wiper is passing over the terminals of busy trunks, but will become deenergized and stop the wiper when an idle trunk is reached.
17. In automatic switching apparatus, a selector switch containing a plurality of rows of fixed bank terminals with a circuit connected to each terminal and means to maintain a distinctive test potential on the terminals of circuits which are busy, a spindle in the switch carrying a test wiper adapted to coöperate with the bank terminals, means to drive the spindle so as to bring the wiper into association with a predetermined row of terminals and thereby with a predetermined group of circuits, a test relay having its winding externally controlled on one side and branched on the other, contacts in one branch normally closed to complete the circuit by the switch spindle when in its normal or inactive position, contacts in the other branch normally open but closed when the relay is energized to complete the branch to the test wiper, and means for driving the spindle and its wiper along a row of terminals for individual test thereof, controlled by the test relay.
18. In automatic switching apparatus, selector switches containing multiple terminals arranged in groups, a wiper in each switch coöperating with said terminals and adapted to be driven to each group, and a test relay for each switch externally controlled on one side and having its circuit branched on the other, with initial energizing means external to the relay and locking terminals within itself adapted when closed to connect it through the second branch to the test wiper.

19. In automatic switching apparatus, selector switches containing multiple terminals arranged in rows or groups, a wiper in each switch coöperating with said terminals and adapted to be driven to each group, and a test relay for each switch externally controlled on one side and having its circuit branches on the other, with initial energizing means external to the relay and locking terminals within itself adapted when closed to connect it through the second branch to the test wiper, and when opened one of said terminals acting to place busy test potential on the test wiper.

20. In a selector switch, bank contacts including connective terminals and test terminals therefor, connective and test wipers, trunk conductors and a test relay associated with said wipers respectively, electromagnetic actuating means for the switch, an actuating circuit, and contacts controlled by the test relay adapted upon energization thereof to connect said actuating circuit to the switch actuating means and upon deenergization to disconnect the same from the actuating apparatus and connect it to the trunk conductors and thence through the switch to the selected circuit when its functioning is complete.

21. In automatic switching apparatus link circuits for building up connections by percentage trunking, an automatic selector switch forming the terminal of one link and containing test multiple contacts of other links in advance, electromagnetic actuating means for the switch, and a test relay acting to connect the said actuating means in operative relation with an impulse sending device at a distant point during the functioning of the switch, and to disconnect it while impulses are sent from such impulse sending device through the switch to a succeeding switch in a selected link.

22. In automatic switching apparatus for percentage trunking, a selector switch forming the terminal of a link and containing in its banks multiple terminals of other links in advance, stepping magnets for said switch, a test wiper, a test relay, an impulse circuit, and contacts in the test relay normally closed to connect the impulse circuit through the switch, with other contacts normally open included in a branch circuit from the impulse circuit to the stepping magnets, whereby the energization of the test relay during the functioning of the switch will disconnect the impulse circuit from the switch wipers and trunk wires and connect it to the stepping magnet, and vice versa.

23. In automatic switching apparatus, a plurality of links for building up connections by percentage trunking, automatic selector switches in the links, electromagnetic actuating means for the switches, controlling

- relays for said actuating means, and electro-magnetic means in each link maintained continuously energized during the switching act to maintain said relays in connection for that link until the next link is determined and connected, and then acting automatically to disconnect the relays.
24. In automatic switching apparatus for percentage trunking, successive links, switch actuating magnets for each link, repeating relays for the switching magnets in each link, and electro-magnetic means maintained continuously energized during the selective functioning in each link to maintain said relays in connection therewith until the succeeding link is selected, and then automatically acting to disconnect said relays.
25. In automatic percentage trunking apparatus, a succession of links or trunks, switching magnets and repeating relays for each link normally disconnected, and means for automatically cutting on the repeating relays of each link upon the seizure of that link and cutting off the repeating relays from each link as that link is established in the course of building up a connection.
26. In a telephone exchange system, an automatic selector switch having connective and test wipers, electromagnetic actuating apparatus therefor, trunk conductors connected to the connective wipers, a test relay associated with the test wiper and adapted to lock thereon during testing, and a cut-off relay having contacts controlling the continuity of the trunk conductors to prevent signaling back and a contact controlling the circuit of said test relay.
27. In a telephone exchange system, an automatic selector switch having connective and test wipers, electromagnetic actuating apparatus therefor, trunk conductors connected to the connective wipers, a test relay associated with the test wiper and adapted to lock thereon during testing, and a cut-off relay having contacts controlling the continuity of the trunk conductors to prevent signaling back and a contact controlling the circuit of said test relay, together with a sending device for controlling the switch actuating apparatus, and means associated therewith to close the circuit of the cut-off relay.
28. In a telephone exchange system, an automatic selector switch having connective and test wipers, electromagnetic actuating apparatus therefor, trunk conductors connected to the connective wipers, a test relay associated with the test wiper and adapted to lock thereon during testing, and a cut-off relay having contacts controlling the continuity of the trunk conductors to prevent signaling back and a contact controlling the circuit of said test relay, together with an operator's circuit, an impulse sender associated therewith, means to connect said circuit and sender to the selector switch, and means becoming operative in the use of the sender to close the circuit of the cut-off relay.
29. In a telephone exchange system, an automatic selector switch having connective and test wipers, electromagnetic actuating apparatus therefor, trunk conductors connected to the connective wipers, a test relay associated with the test wiper and adapted to lock thereon during testing, and a cut-off relay having contacts controlling the continuity of the trunk conductors to prevent signaling back and a contact controlling the circuit of said test relay, together with an operator's circuit, an automatic switch forming a terminal thereof and adapted to become connected with the selector switch and its trunk conductors, in response to the initial operation thereof, an impulse sender controlled by the operator, means associated with said sender for predetermining and setting up the number to be transmitted, a starting key adapted to effect transmission of the number set up, and circuit connections controlled by said key and extending through the operator's switch connection to the cut-off relay of the selector switch trunk, whereby the starting of the number will simultaneously break the trunk and place the switch in condition for actuation.
30. In a telephone exchange system, line circuits, link circuits to interconnect the same, a selector switch forming the terminal of a link containing connective and test contacts, with co-operating connective and test wipers, actuating magnets for the switch, energizing circuits therefor, a test relay controlling said circuits to cut on the magnets for actuating the switch and to cut them off to let impulses go to the next switch in series, means for locking said relay on the test wiper after initial movement of the switch in testing, a cut-off relay controlling the link conductors to the switch to prevent back signaling, an operator's circuit and an automatic switch for connecting the same to the link circuits between their cut-off relays and their selector switches, a sending machine and means for setting up a number in terms of impulses to be transmitted from said machine, an operator's telephone, means for connecting the same through the operator's circuit to the link, a starting key for the sending machine, and circuit connections for the link cut-off relay controlled in the actuation of the starting key, together with an initial energizing circuit for the test relay controlled by the cut-off relay.
31. In a telephone exchange system, a plurality of line circuits, link circuits for interconnecting the same, primary selector switching means acting in response to calls over the lines to connect a calling line to

- an idle link circuit, an operator's circuit, secondary selector switching means for connecting the operator's circuit with the links, means acting to lock a subscriber's line 5 in connection with a link and through the secondary selector switching means with the operator's circuit, and means controlled by the operator to unlock and release the same.
32. In a telephone exchange system, a plurality of line circuits, link circuits for interconnecting the same, primary selector switching means acting in response to calls over the lines to connect a calling line to an idle link circuit, an operator's circuit, 10 secondary selector switching means for connecting the operator's circuit with the links, means acting to lock a subscriber's line beyond his control, in connection with a link and through the secondary selector switching means with the operator's circuit, a key 15 for the operator's circuit, and means for unlocking the subscriber's line connection in the use of said key by the operator, whereby the subscriber may effect release of his line by restoring the receiver to its hook after the operator has answered the call, only.
33. In a telephone exchange system, a plurality of line circuits, link circuits with 20 terminal automatic switches for interconnecting the lines including a connector link and a connector switch containing called line terminals, a cut-off relay having contacts adapted to sever the connector link during 25 operation of the switch, actuating magnets for the switch, and repeating relays having their windings connected to the incoming end of the same link to receive actuating impulses through a preceding link connection, and containing contacts included in the circuits of the switch actuating magnets, whereby the initiating or incoming end and the calling or switch end of the connector link are separated during the selection 30 and calling of a wanted subscriber, without interference with other lines over which the switch wipers may pass or false signals.
34. In a telephone exchange system, a plurality of line circuits, link circuits with 35 terminal automatic switches for interconnecting the lines including a connector link and a connector switch containing called line terminals, a cut-off relay having normally disconnected contacts adapted to maintain severed the connector link during operation of the switch, actuating magnets for the switch, and repeating relays connected to the incoming end of the link to receive actuating impulses through a preceding link connection, 40 and containing contacts included in the circuits of the switch actuating magnets, together with external means to energize the cut-off relay after the subscriber's line is selected and connected, so as to restore the continuity of the link circuit.
35. In a telephone exchange system, a plurality of line circuits, link circuits with terminal automatic switches for interconnecting the lines including a connector link and a connector switch containing called line terminals, a cut-off relay having contacts adapted to sever the connector link during operation of the switch, actuating magnets for the switch, and repeating relays connected to the incoming end of the link to 45 receive actuating impulses through a preceding link connection, and containing contacts included in the circuits of the switch actuating magnets, together with means becoming operative after the wanted subscriber's line has been selected and connected, to operate the cut-off relay to restore the continuity of the link circuit, and to disconnect the said repeating relays.
36. In a telephone exchange system, a plurality of line circuits, link circuits with terminal automatic switches for interconnecting the lines including a connector link and a connector switch containing called line terminals, a cut-off relay having contacts adapted to sever the connector link during operation of the switch, actuating magnets for the switch, and repeating relays connected to the incoming end of the link to receive actuating impulses through a preceding link connection, and containing contacts included in the circuits of the switch actuating magnets, together with a pair of battery supply relays associated with the switch end of the link, means to disable the 50 same during the operation of the switch, release means for the switch controlled by one of said relays in response to the act of a called subscriber after he has answered the call, and means becoming operative after the wanted subscriber's line is selected and connected to operate the cut-off relay to restore the continuity of the link circuit to disconnect the repeating relays and to connect the battery supply relays.
37. In a telephone exchange system, a plurality of line circuits, link circuits with terminal automatic switches for interconnecting the lines including a connector link and connector switch containing called line terminals, actuating magnets for the switch, means for transmitting impulses thereto through the link circuit, an auxiliary selective switch associated with the connector switch, an actuating magnet therefor, means to transmit impulses thereto for selection through the connector link circuit, and a plurality of selective ringing devices connected to and controlled by said auxiliary switch.
38. In a telephone exchange system, a plurality of line circuits, link circuits with terminal automatic switches for interconnecting the lines including a connector link and connector switch containing called line terminals,

- minals, actuating magnets for the switch, means for transmitting impulses thereto through the link circuit, an auxiliary selective switch associated with the connector switch, an actuating magnet therefor, means to transmit impulses thereto for selection through the connector link circuit, a plurality of selective ringing generators connected to said auxiliary switch, and a ringing relay in the connector circuit having contacts adapted to be connected through the auxiliary switch to a preselected generator, with means to energize said ringing relay to connect the selected generator through the connector switch terminals to the wanted subscriber's line.
39. In a telephone exchange system, a plurality of line circuits, link circuits with terminal automatic switches for interconnecting the lines including a connector link and connector switch containing called line terminals, actuating magnets for the switch, means for transmitting impulses thereto through the link circuit, an auxiliary selective switch associated with the connector switch, an actuating magnet therefor, means to transmit impulses thereto for selection through the connector link circuit, a plurality of selective ringing generators connected to said auxiliary switch, and a ringing relay in the connector circuit having contacts adapted to be connected through the auxiliary switch to a preselected generator, with means automatically controlled after the complete operation of both the connector and auxiliary switches, to energize said ringing relay and connect the selected generator to the wanted subscriber's line.
40. 40. In a telephone exchange system, a plurality of line circuits, link circuits with terminal automatic switches for interconnecting the lines including a connector link and connector switch containing called line terminals, actuating magnets for the switch, means for transmitting impulses thereto through the link circuit, an auxiliary selective switch associated with the connector switch, an actuating magnet therefor, means to transmit impulses thereto for selection through the connector link circuit, a plurality of selective ringing generators connected to said auxiliary switch, and a ringing relay in the connector circuit having contacts adapted to be connected through the auxiliary switch to a preselected generator, with means automatically controlled after the complete operation of both the connector and auxiliary switches, to energize said ringing relay during recurring intervals, and during the alternate non-ringing intervals to place the ringing relay under control of the wanted subscriber in answering the call.
41. In a telephone exchange system, line circuits, link circuits and automatic switches forming terminals thereof for interconnecting the lines, actuating and releasing means for each automatic switch, auxiliary selector switches associated with certain of said automatic switches, actuating and restoring magnets therefor, circuit connections therefrom to the releasing mechanism of the associated automatic switches, adapted to be closed in the last movement of said auxiliary switches on being restored to their normal or inactive position, and means for controlling the release magnets of the auxiliary switches through the connective link circuits.
42. In a telephone exchange system, line circuits, selector and connector switches for interconnecting the same, actuating and release magnets for said switches, an auxiliary switch associated with each connector switch, actuating and restoring magnets for each auxiliary switch, means for transmitting impulses through a connector link circuit to actuate the associated auxiliary switch, contacts in each auxiliary switch adapted to be closed a definite time interval after the actuation of its restoring magnet, and a circuit connection from said contacts to the release magnet of the associated connector switch.
43. In a telephone exchange system, line circuits, link circuits with terminal automatic switches including line connectors, for interconnecting the lines, actuating and release magnets for each connector switch, relays connected in circuit with each connector switch, responsive to the acts of subscribers connected therethrough, an auxiliary step by step switch for each connector, means to drive said auxiliary switch in response to impulses through the connector circuit, means to drive said switch forward by additional impulses to restore it to normal or connective position, contacts closed in said switch in its restoring movement, and a circuit connection from said contacts to the release magnet of its associated connector.
44. In a telephone exchange system, line circuits, link circuits, including a connector link and a connector switch therefor containing connective line terminals, actuating and release magnets for said switch, an auxiliary ringing selector switch associated with the connector, a stepping magnet for said auxiliary switch, a contact arm therefor, ringing selector contacts coöperating with said arm in the first part of its travel from normal or inactive position, release contacts closed at a later point in the travel of said switch, means for transmitting impulses through the connector link circuit, means to direct said impulses to an actuat-

ing magnet of the selector switch and the actuating magnet of the ringing selector switch in proper alternation, and a circuit connection from the release magnet of the connector switch to the release contacts of the auxiliary switch.

45. In a telephone exchange system, a plurality of line circuits, selector and connector switches with link or trunk circuits therefor, actuating and release magnets for each connector, a step by step auxiliary ringing selector switch associated with a connector, repeating relays also associated with said connector, means for transmitting actuating impulses for selective purposes to said relays, circuit connections from said relays to the actuating magnets of the connector switch, other circuit connections from said relays to the actuating magnet of the said auxiliary switch, means to close each of said circuit connections automatically to repeat the proper predetermined sets of impulses to the connector switch and the auxiliary switch respectively, and a ringing relay coöperating with said auxiliary switch to connect a selected generator through the connector switch to the line of a wanted subscriber.

46. In a telephone exchange system, a plurality of line circuits, selector and connector switches with link or trunk circuits therefor, actuating and release magnets for each connector, a step by step auxiliary ringing selector switch associated with a connector, repeating relays also associated with said connector, means for transmitting actuating impulses for selective purposes to said relays, circuit connections from said relays to the actuating magnets of the connector switch, other circuit connections from said relays to the actuating magnet of the said auxiliary switch, means to close each of said circuit connections automatically to repeat the proper predetermined sets of impulses to the connector switch and the auxiliary switch respectively, a contact in the auxiliary switch closed in the last part of its travel after completing its selective functions, and a circuit connection from said contact to the release magnet of the connector switch.

47. In a telephone exchange system, a plurality of line circuits, selector and connector switches with link or trunk circuits therefor, actuating and release magnets for each connector, a step by step auxiliary ringing selector switch associated with a connector, repeating relays also associated with said connector, means for transmitting actuating impulses for selective purposes to said relays, circuit connections from said relays to the actuating magnets of the connector switch, other circuit connections from said relays to the actuating magnet of the said

auxiliary switch, means to close each of said circuit connections automatically to repeat the proper predetermined sets of impulses to the connector switch and the auxiliary switch respectively, a battery supply relay in the connector circuit responsive to flow of current in the wanted subscriber's line, means for placing said relay in connection with said line after the connector switch has completed its functioning, a restoring circuit for the auxiliary switch controlled by said relay, and a release circuit for the connector switch controlled by the auxiliary switch.

48. In a telephone exchange system, line circuits, automatic switching apparatus for interconnecting the same, an operator's circuit, secondary selector means automatically actuated in response to calls, to connect said operator's circuit to the automatic switching apparatus and to calling lines, an operator's equipment including impulse sending means, a telephone set and separable circuit connections from said telephone set to the operator's circuit, together with means controlled in the completion and separation of the elements of said circuit connections, adapted to render said secondary selector switching means active or inactive, whereby the operator's position is rendered "dead" when her telephone set is disconnected.

49. In a telephone exchange system, line circuits, automatic switching apparatus and connective links for the same, an operator's circuit, secondary switching means acting in response to calls to automatically connect the operator's circuit to a switch link and a calling line, an impulse sender, a telephone set, and a plug and jack connection between said telephone and the operator's circuit, together with a control circuit for the secondary switching means completed through contacts of said plug and jack when connected.

50. In a telephone exchange system, a plurality of line circuits, link circuits and automatic switches for interconnecting the lines, a plurality of operator's circuits terminating at different operator's positions, secondary selector switches acting automatically in response to calls to connect the operators' circuits to switch links and calling lines, automatic distributing means adapted to control the secondary selector switches so as to connect the operators' circuits in rotation for successive calls, impulse sending means for the operators, a telephone set for each operator and a separable connection between each operator's telephone and each operator's circuit, together with controlling circuits for the respective secondary selector switches completed through said separable connections, whereby the withdrawal of an operator from her position and the discon-

nection of her telephone will secure rotation of calls among the remaining positions only.

51. In a telephone exchange system, line circuits, link circuits to interconnect the same, a selector switch forming the terminal of a link containing connective and test contacts, with coöperating connective and test wipers, actuating magnets for the switch, energizing circuits therefor, a test relay controlling said circuits to cut on the magnets for actuating the switch and to cut them off to let impulses go to the next switch in series, means for locking said relay on the test wiper after initial movement of the switch in testing, a cut-off relay controlling the link conductors to the switch to prevent back signaling, an operator's circuit and an automatic switch for connecting the same to the link circuits between their cut-off relays and their selector switches, a sending machine and means for setting up a number in terms of impulses to be transmitted from said machine, an operator's telephone, means for connecting the same through the operator's circuit to the link, a starting key for the sending machine, and circuit connections for the link cut-off relay controlled in the actuation of the starting key, together with an initial energizing circuit for the test relay also controlled in the actuation of the starting key.

52. An automatic switch for selective systems, comprising the following instrumentalities: a bank of contacts arranged in vertical rows, a spindle carrying a wiper arm adapted to effect engagement with the contacts in any row by reciprocating along the same, a set of group contacts, alined with the respective rows, and a wiper carried on the spindle adapted to engage said group contacts.

53. An automatic switch for selective systems, comprising the following instrumentalities: a bank of contacts arranged in vertical rows, a spindle carrying a wiper arm adapted to effect engagement with the contacts in any row by reciprocating along the same, a set of group contacts, alined with the respective rows, and a wiper carried on the spindle adapted to engage said group contacts when the spindle is in position to disengage the first mentioned wiper arm from any contact row.

54. An automatic testing selector switch comprising a bank of individual test contacts arranged in a curved series of straight rows, a series of row contacts, one for each row, a spindle carrying an individual test wiper normally out of engagement with all the rows, and a row test wiper alined with the individual wiper, and adapted to engage the row test contacts when the spindle is in normal position, but to leave the same when

the spindle reciprocates to carry the individual test wiper along the contacts in any row.

55. In an automatic testing selector switch, individual and row test contacts, a spindle having rotary and reciprocating motion, and adapted to test the row contacts in one motion, and the individual contacts in the other, and a row test wiper comprising a supporting anvil secured on the spindle in alinement with the individual test wiper, and a spring wiper arm secured to and projecting over said anvil so as to rest thereon under normal tension, whereby said row test may be adjusted for exact contact in the plane of the row test terminals, and may transfer its pressure thereto without compensating pressure from the opposite side.

56. In a telephone exchange system, line circuits, automatic switching apparatus therefor including a connector switch and circuit, metallic circuit links extending between the several switches and terminating in wipers thereof, a third conductor associated with each pair of link conductors, terminating at the third wiper associated with the link wipers of the switch, actuating and release means for each switch, and a master relay in the connector circuit controlling the local actuating and release circuits thereof, and adapted to be energized and self-locked by current through the third conductor of its connector circuit, and through the third conductors of a preceding link or links connected thereto.

57. In a telephone exchange system, line circuits, a plurality of link circuits terminating in automatic switches, including selector and connector links and switches, metallic circuit conductors terminating in connective wipers for each link, an associated third conductor terminating in a test wiper for each link, release magnets in the links connected to said third conductors while the links are in series with each other, and means under control of a calling subscriber to originate a release impulse and send it forward from the first link, through the third conductors in succeeding links, to energize the release magnets thereof.

58. In a telephone exchange system, line circuits, link circuits terminating at one end in primary selectors and at the other in selective switches, auxiliary links and switches including a connector switch, means for actuating said switches to connect a calling and a called line, a relay in the primary selector link responsive to the acts of the calling subscriber, metallic circuit conductors and an associated third conductor in each link brought into connection through succeeding links when connected, release magnets connected in the several links to

said third conductor, and means controlled by said primary link relay to originate and send forward a current impulse through the connected third conductors to energize said 5 release magnets.

59. In a telephone exchange system, line circuits, link circuits terminating at one end in primary selectors and at the other in selective switches, auxiliary links and switches 10 including a connector switch, means for actuating said switches to connect a calling and a called line, a relay in the primary selector link responsive to the acts of the calling subscriber, metallic circuit conductors 15 and an associated third conductor in each link brought into connection through succeeding links when connected, release magnets connected in the several links to said third conductor, means controlled by said 20 primary link relay to originate and send forward a current impulse through the connected third conductors to energize said release magnets, a master relay in the connector circuit controlling the actuating and release circuits thereof, until the called subscriber answers locked on said 25 third conductor, together with a link relay responsive to current in the called subscriber's line adapted to release said master relay when the subscriber answers, and shift the control of the release from the primary link relay to the connector link relay.

60. In a telephone exchange system, line circuits, link circuits terminating at one end 30 in primary selectors and at the other in selective switches, auxiliary links and switches including a connector switch, means for actuating said switches to connect a calling and a called line, a relay in the primary se-

lector link responsive to the acts of the calling subscriber, metallic circuit conductors and an associated third conductor in each link brought into connection with each other through succeeding links when connected, release magnets connected in the several 35 links to said third conductor, means controlled by said primary link relay to originate and send forward a current impulse through the connected third conductors to energize said release magnets, a master relay 40 in the connector circuit controlling the actuating and release circuits thereof, until the called subscriber answers locked on said third conductor, together with a link relay responsive to current in the called subscriber's line adapted to release said master relay when the subscriber answers, and shift the control of the release from the primary link relay to the connector link relay.

61. In an automatic switch for telephone 55 systems, bank contacts, a spindle, a radial arm rigidly fixed to said spindle, an abutment on said arm at one point, and a wiper secured on said arm at another point and resting under initial tension against said 60 abutment.

In testimony whereof I affix my signature in presence of two witnesses.

EDWARD E. CLEMENT.
